COMBINED AUTOMATIC SEWING ASSEMBLY
Herbert Jacobs and Herschel Baron, Philadelphia, and
Eric Winston, Melrose Park, Pa., said Baron and said
Winston assignors to Jacobs Machine Corporation,
Philadelphia, Pa., a corporation of Pennsylvania
Continuation-in-part of application Ser. No. 467,911,
June 29, 1965. This application June 12, 1967, Ser.
No. 660,143

29 Claims. (Cl. 112—2)

ABSTRACT OF THE DISCLOSURE

A combined automatic sewing assembly having feeding means including reciprocable feeder foot means operative to contact the topmost piece of porous cloth that is stacked in a pile. The reciprocable feeder foot means separate the topmost workpiece from the remainder of the pile in a lifting action with the feeder foot means having adhesive means for engagement with the topmost workpiece in order to achieve the aforesaid lifting action. The feeder foot means also have vacuum means that are activated during the lifting action in order to assist the adhesive means in maintaining contact with the workpiece during the lifting action. In another embodiment of the invention a pin extends from the vacuum means to engage the workpiece and assists in urging the workpiece forwardly following the aforesaid lifting action in order to project the workpiece towards feed rollers. In another embodiment of the invention the adhesive means are dispensed with, such that the lifting and feeding action is achieved with the vacuum means-pin combination.

Other features may be associated with the feeding means including a sewing station, cutting means and stacking means.

This application is a continuation-in-part application based on application Ser. No. 467,911 filed June 29, 1965, and entitled, "Improved Automatic Sewing Assembly," now abandoned.

This invention relates to a sewing apparatus and has as its objective the provision of an improved automatic sewing machine assembly.

With the rise of foreign competition in the textile field, it has become incumbent upon domestic manufacturers to increase productivity in order to overcome a financially unfavorable wage differential.

Therefore, many attempts have been made in the past years to automate the various sewing processes.

Such prior attempts have been successful to some degree, but the ultimate goal, namely, to achieve a sewing apparatus which is fully automated is yet to be achieved.

In Jacobs Patent No. 3,223,059 there was disclosed and claimed an automatic sewing apparatus which basically comprised a feeder station, a sewing station, a cutting station and a stacking station. As a part of the assembly of the automatic sewing apparatus of said Patent No. 3,223,059, there was provided a feeder foot which was actuated by a feeder belt assembly that included adhesive means. When the feeder foot went through a rocking cycle, it pressed an area of adhesive tape against the upper surface of the topmost piece of stacked pieces of goods. As the feeder foot stepped upwardly and forwardly, it carried said topmost piece of goods with it to rollers which then conveyed the piece of goods towards a sewing station. When the piece of goods approached the sewing station a sewing machine was turned on through the utilization of photosensitive means. At the same time bind-

2

ing was fed to the sewing machine in order to be sewn to a piece of goods. After the sewing operation was completed, the sewn goods were further advanced toward a cutting station. Additional photosensitive means were utilized to actuate a cutter in the cutting station at the proper time so that the sewn binding would be severed at a desired point. The goods were finally conveyed to a stacking station preparatory to the initiation of further operation or final packing.

10 The automatic sewing apparatus of said Patent No. 3,223,059 has operated satisfactorily and has achieved the objectives set forth therein.

However, certain improvements in the basic mechanism disclosed in said Patent No. 3,223,059 have been made such that the operation of the combined automatic sewing apparatus is now even more satisfactory and more dependable, and furthermore these improvements have greatly increased the versatility of the basic mechanism.

It is, accordingly, a prime objective of the present invention to provide a combined sewing assembly which is fully automatic.

A further object of the present invention is to provide a combined automatic sewing assembly with complementary feeding means, sewing means, cutting means and stacking means.

A still further object of the present invention is to provide a combined feeding means for use with an automatic sewing apparatus.

Yet another object of the present invention is to provide a combined automatic sewing assembly which incorporates air cylinders to provide the various basic movements required for operation of the machine.

A still further object of the present invention is to combine with a combined automatic sewing assembly, folding means and holding means which are operative through the strategic positioning of a plurality of air jets.

A still further object of the present invention is to provide improved cutting means for use in a combined automatic sewing assembly.

40 The foregoing as well as other objects of the invention are achieved by providing a combined automatic sewing assembly which basically comprises a feeder station, a sewing station, a cutting station and a stacking station.

45 In the specific embodiment to be detailed hereinafter, a continuous binding is automatically sewn to a cut sleeve, but it should be understood that many other sewing variations obtainable with the present invention will readily occur to those skilled in the art.

50 The feeding station basically comprises a platform for holding the stacked cut sleeves, and a feeder assembly including a feeder foot for depositing the cut sleeves, one-by-one, onto a conveyor belt to the sewing machine.

55 The sewing machine is automatically activated by photosensitive means, and the cutting means are also activated by photosensitive means.

A stacking station is provided to automatically stack the product after the sewing and cutting operations have been completed.

60 Automatic stopping controls are associated with both the feeder platform and stacking means for emergency purposes as when the feeder supply is exhausted or the adhesive means have been wound to capacity on a take-up roll. Various other safety features and warning devices are associated with the present invention, such as, warning lights and automatic turn-off devices in the event undesirable conditions develop.

65 Other objects and many of the attendant advantages of this invention will be readily appreciated as the same becomes better understood by reference to the following detailed description when considered in connection with the accompanying drawings wherein:

FIG. 1 is a plan view of the complete assembly of the present invention;

FIG. 1A is an enlarged elevational view taken along the lines 1A—1A of FIG. 1;

FIG. 1B is an enlarged detail view of the lever assembly of FIG. 1A;

FIG. 15 is an enlarged detail view showing the sewing area;

FIG. 15A is an enlarged elevational view taken along the lines 15A—15A of FIG. 15;

FIG. 16 is a plan view with portions in section taken along the lines 16—16 of FIG. 15;

FIG. 17 is a sectional view taken along the lines 17—17 of FIG. 16;

FIG. 18 is an elevational view of the rear end of the present invention taken along the lines 18—18 of FIG. 1;

FIG. 18A is an enlarged sectional view taken along the lines 18A—18A of FIG. 18;

FIG. 18B is a sectional view taken along the lines 18B—18B of FIG. 18;

FIG. 19 is a perspective view diagrammatically showing the chain and sprocket train for driving certain of the operative elements of the present invention;

FIG. 20 is an enlarged and elevational view taken along the lines 20—20 of FIG. 18;

FIG. 21 is a sectional view taken along the lines 21—21 of FIG. 20;

FIG. 22 is an enlarged detail elevational view taken along the lines 22—22 of FIG. 20;

FIG. 23 is a sectional view taken along the lines 23—23 of FIG. 21;

FIG. 24 is a sectional view taken along the lines 24—24 of FIG. 21;

FIG. 25 is an enlarged elevational view with portions in section taken along the lines 25—25 of FIG. 21;

FIG. 26 is an enlarged sectional view taken along the lines 26—26 of FIG. 25;

FIG. 27 is an enlarged sectional view taken along the lines 27—27 of FIG. 25;

FIG. 28 is essentially an enlarged plan view taken along the lines 28—28 of FIG. 25;

FIG. 29 is a fragmentary perspective view of a scaffolding system;

FIG. 30 is an enlarged elevational view of one of the scaffolding clips;

FIG. 31 is a sectional view taken along the lines 31—31 of FIG. 30; and

FIGS. 32, 33 and 34 are schematic wiring diagrams showing further details of the operation of the present invention.

Referring now in greater detail to the various figures of the drawings wherein similar reference characters refers to similar parts, a combined automatic sewing machine embodying the present invention is generally shown at 10 in FIG. 1. The combined automatic sewing assembly of the present invention basically comprises a feeder station 12, a sewing station 14, a cutting station 16 and a stacking station 18.

The basic details of the feeder station are shown in FIGS. 2 and 3 with subsidiary details thereof being shown in FIGS. 4 to 13 of the drawing.

The feeder station 12 is composed of a supply area 20 (FIGS. 4 to 6A inclusive), feeder foot means 22 (FIGS. 8 to 10A inclusive) and miscellaneous drive means 24 (FIGS. 7 and 11 to 13 inclusive).

It is the prime function of the feeder station 12 to pick a workpiece 26 up from the supply area 20 and transport the workpiece 26 toward the sewing section 14 at a desired rate. It is also contemplated that the feeder station 12 will include means for folding or lapping the work.

The supply area 20 is shown in great detail in FIGS. 4 to 6A wherein the workpieces 26 are placed in a stacked arrangement upon a platform 28 (FIG. 5) which extends from the frame 30 of the machine 10. The supply area 20 includes support bars 32 which are bolted to the frame 30 as shown in FIG. 4. A cross bar 34 has its ends releasably clamped to each of the support bars 32 by clamps 36, and two brackets 38 (FIG. 4) depend from the cross bar 34 and are secured thereto by adjustable clamps 40. Secured to one of the brackets 38 adjacent one end thereof is a clamp bar 42 which is positioned generally parallel to the support bars 32 but lying somewhat below the support bars 42 as shown in FIG. 5. Limit bar 44 is secured to the other bracket 38. As shown in FIG. 4, the forward end of the clamp bar 42 and the forward end of the limit bar 44 is secured to the frame 30 of the machine and particularly to angle members 46 thereof.

Slidably mounted upon the clamp bar 42 are a series of clamp brackets 48, each of which carry a rod 50 which may be spring loaded via springs 51 as shown in FIG. 4. As further shown in FIG. 4, adjustment means 53 for rod 50 are provided, and one end of the rod 50 carries a locating and retention finger 52 that may be secured on rod 50 by means of a simple bolt and nut arrangement with the band of the bolt 54 being shown in FIG. 4.

The details of the locating retention fingers 52 are shown in FIGS. 6 and 6A wherein the fingers 52 are shown to comprise a depending clip 56 with a flared out end 58. The clip 56 also includes a horizontal portion which is held by the bolt 54. Immediately lying above the horizontal portion is an L-shaped member 60 which has a vertically disposed cushion 62 secured thereto as shown

in FIG. 6. As further shown in FIG. 6A, the cushion 62 may be adjusted with respect to the workpieces 26 by sliding the L-shaped member 60 with respect to the bolt 54 as permitted by virtue of the shape of the elongated slot 63 (FIG. 6A) through which the stem of the bolt 54 passes.

The limit bar 44 is shown in FIGS. 4 and 6 as being a continuous bar having an elongated cushion 64 secured thereto, and also having a clip 66 with a flared end in a manner similar to the clip 56. A bolt 68 may be provided to secure the backing for the cushion 64 and the extension of the clip 66 together in the manner of FIG. 6.

As shown in FIG. 4, the rods 50 may be so adjusted using adjustment means 53 that the fingers 52 may be positioned against the edges of the stack of irregularly shaped workpieces 26 so that the fingers 52 will have a function of retaining the stack of workpieces 26 in an orderly state and also to resist the picking up of more than one workpiece at a time, due to fiber entanglement. The limit bar 44 is positioned to counteract any undue tendency of the fingers 52 to disrupt the orderly state of the stacked workpieces 26, and thus the limit bar 44 has the function of preventing overcompensation by virtue of the movement of the fingers 52. The confining nature of the fingers 52 as opposed to the limiting action of the limit bar 44 is clearly shown in FIG. 6 of the drawing.

As will be discussed in greater detail hereinafter, the platform 28 is gradually raised as the workpieces 26 are fed one-by-one toward the sewing station 14 so that the level of the topmost workpieces will be essentially constant. This is necessary in order that the feeder foot means 22 of the present invention may operate upon the topmost workpiece in order to lift the topmost piece from its stacked position of FIG. 6 and carry it upwardly and then forwardly so that it can start its journey toward the sewing station 14. The mechanism achieving the gradual raising of platform 28 forms no part of the present invention but is rather well known in the duplicating machine art as represented in certain patents such as 1,963,694, 2,083,296 and Re. 20,581.

The feeder foot means 22 are shown in more detail in FIGS. 8 to 10A inclusive of the drawing. The cyclical action of the feeder foot 70 is illustrated in FIG. 10A wherein the feeder foot first moves downwardly to low position 70' as shown in phantom in FIG. 10A. As the feeder foot 70 moves downwardly it contacts the upper surface of the topmost workpiece 26. Adhesive means associated with the feeder foot 70 contact the workpiece 26, and thus when the feeder foot 70 moves upwardly to the full line intermediate position of FIG. 10A, a piece of work 26 is adhered thereto. At this point suction means, to be described hereinafter, as associated with the feeder foot 22, are activated to carry the weight of the work 26. The feeder foot 70 then kicks forwardly to the position indicated at 70" in FIG. 10A and thereafter the goods are carried away from the feeder foot by the action of forwardly moving rollers.

As shown in FIG. 10, the feeder foot 70 depends from adhesive tape housing 72 and is an integral part thereof as will be discussed hereinafter. The housing 72 is rigidly mounted upon a support roller 74 which not only rocks to achieve the forward kicking action of the feeder foot 70 but which also is movable up and down to achieve the lifting action of the feeder foot 70.

The three positions of the feeder foot 70 as it undergoes its cycle motion are illustrated in FIG. 10A. As will be discussed in greater detail hereinafter, adhesive means 76 are carried along the feeder foot 70 during its cycle of movement in order that the topmost workpiece 26 (FIG. 10) may be bodily lifted and led to serrated first transport roller 78 (FIG. 7 and FIG. 10A). The intermediate position of the feeder foot 70 is shown in full line on FIG. 10A. In the discussion to follow it will be assumed that the feeder foot 70 will move downwardly through the position 70' of FIG. 10A.

As the feeder foot 70 completes its downward stroke, it will be seated upon the topmost workpiece 26, the adhesive tape means 76 will thereupon contact the topmost workpiece 26 so that when the feeder foot 70 again lifts to the full line intermediate position of FIG. 10A, the topmost workpiece 26 will accordingly be carried upwardly. Hence, when the feeder foot 70 kicks forwardly to the position 70" of FIG. 10A, the topmost workpiece 26 will be carried upon the serrated transport roller 78.

At this point, the positive forward pulling action of the first transport roller 78 and complementary vertically aligned short rubber roller 80 will overcome the holding power of the adhesive tape means 76 to carry the workpiece 26 forwardly. As will be discussed in greater detail hereinafter, suction means 82 are employed to assist the adhesive tape means 76 in the holding action. In particular, the suction means 82 will be turned on immediately after the feeder foot 70 has started to lift upwardly from its lowermost position 70'. In this way, the suction means 82 will not cause more than one porous cloth workpiece 26 to be lifted.

It is to be understood that the movements of feeder foot 70 bring about a separation of the topmost piece of porous cloth from the remaining pieces of cloth in the stack. This is accomplished by an initial upward pulling action exerted by the feeder foot upon the topmost workpiece, followed by an upwardly kicking step. It should be kept in mind that whereas the front portion of the topmost workpiece will be lifted in the initial movement of feeder foot 70 that the remainder of the workpiece is draped in the stack. It is therefore necessary on the forwardly kicking step to cause relative dragging of the topmost workpiece with respect to the remainder of the stack. Sometimes it is necessary to overcome fiber entanglement or other internal forces which tend to cause the various pieces of cloth in the stack to adhere to each other. This adherence becomes more pronounced as the bottom of the stack is approached in view of the added pressure upon the lower workpieces.

In order to facilitate the forward dragging or separation of the topmost workpiece with respect to the remainder of the stack, the suction means 82 may be fitted with a downwardly extending pin 82A as shown in FIG. 10B wherein the suction means 82 are positioned behind the feeder foot 70. It is to be understood that the pin means 82A may be alternately associated with the feeder foot 70 or otherwise affixed to the feeder foot means 22A while achieving the objectives of the present invention.

The action of the feeder foot means 22A of FIG. 10B can be observed in the four positions of FIG. 10C. In position (1) the feeder foot 70 is moving downwardly toward the porous workpieces including topmost workpiece 26A. In position (2) the tacky adhesive 76 of the feeder foot 70 has contacted the topmost workpiece 26A and the entire feed foot means 22A has begun to lift. However the suction means or vacuum means 82 is not as yet operative. In the third view of FIG. 10C the feeder foot 70 has lifted a sufficient distance (about one-half of an inch) such that the vacuum means 82 has been turned on. The vacuum means now becomes an important source of lift and forward movement in order to separate the topmost workpiece 26A from the remainder of the stack. It is also to be noted that the pin 82A is in firm engagement with the topmost workpiece 26A.

Finally, as shown in the fourth position the feeder foot 70 kicks forwardly to deliver the workpiece 26A to the rollers 78 and 80. Separation of the topmost workpiece 26A, and in particular its forward dragging with respect to the remainder of the stack is enhanced by the engagement of the pin 82A in the topmost workpiece 26A. This produces a definite grip upon the topmost workpiece 26A. It can be readily seen that where desired more than one pin 82A may be utilized on the suction means 82 or that one or more pins may be positioned upon the feeder foot 70 in addition to the pin on the

suction means 82 or may be otherwise strategically distributed on the feeder means 22A.

There is also provided an adjustment knob 82B to facilitate precise positioning of the pin 82A. It is therefore seen that the vacuum means 82 is relied upon to achieve a separation of the topmost workpiece as well as in delivering the topmost workpiece to the rollers 78 and 80. The latter delivery movement is enhanced by the presence of the pin 82A.

While the preferred adhesive means is the tacky adhesive tape 76, it is possible to use other techniques in order to achieve the initial lifting of the topmost piece of cloth. In particular it is possible to use other adhering or grabbing means to raise the forward area of the topmost workpiece a sufficient distance prior to the activation of the vacuum. For instance, static electricity or electrostatic attraction may be utilized. Also, a magnetic means can be used where the piece of cloth itself is made to contain tiny magnetic particles.

A pinching techniques or a frictional engagement either along or in combination with each other can be relied upon for initial lifting. Alternatively, a backward push using a frictional roller to create a bulge that is then picked up by the vacuum means may also be relied on. A grabbing means such as a device with tiny hooks or even the use of a "Velcro" material may also be relied upon for the initial lifting action.

In view of the foregoing the term "adhesive means" as utilized in the specification and claims is to be understood as pertaining to any one of many initial lifting means or techniques which will readily occur to those skilled in the art in view of the teachings of this specification.

As previously stated it is preferred that the front area of the piece of cloth be raised about one-half inch before the vacuum means is turned on with a total lift of one and one-quarter inch. This means that the remaining three-quarters of an inch of lift occurs once the vacuum means have been turned on. The forward kick is for about three-quarters of an inch.

With reference to FIGS. 10D, 10E and 10F, the adhesive means can be dispensed with in connection with certain types of fabrics, such as many so called permanent press fabrics. As shown in FIG. 10D vacuum means 82 with pin 82A and adjustment knob 82B are provided as the feeder foot means 22B. In the first view of FIG. 10E the feeder foot means 22B is moving downwardly toward a stack of porous workpieces 26. In the second view the feeder foot means has reached the bottom of its descent and has lifted upwardly with the vacuum becoming operative at or about the lowest point of the descent. The second view of FIG. 10E shows the vacuum means 82 in a somewhat raised position where the topmost piece of cloth is being held by the vacuum and pin 82A is in engagement. In the third view of FIG. 10E feeder foot means has kicked forwardly with the engagement of pin 82A enhancing the forward dragging action of the topmost piece of cloth with respect to the remainder of the pieces of cloth. Reference is made to FIG. 10F which shows the engagement of the feeder foot means 22B with the topmost piece of cloth 26A.

In this embodiment of the present invention the degree of vacuum must be controlled so that only one piece of cloth at a time is lifted. It has been found that successful picking up using feeder foot means 22B is achieved under a vacuum of about six inches of mercury which rises to about seven inches of mercury once the feeder foot means 22B is lifting a piece of cloth. The preferred idling range is about five to nine inches of mercury, and it has been found that in the range of nine to fourteen inches of mercury that a permanent press fabric with two pieces at a time are usually picked up. Below five inches of mercury pick up of even a single piece tends to be erratic. With the preferred degree of vacuum, it is also preferred that the vacuum become operative at the lowest point in the descent of the feeder foot means 22B, and this is

preferably closely adjacent to the topmost workpiece in the stack.

Where tacky adhesive is used, it is desirable to provide a relatively fresh, tacky adhesive surface to the topmost workpiece 26 at all times, the present invention contemplates an adhesive tape drive mechanism which will advance the adhesive means 76 a sufficient increment as the feeder foot 70 moves through its cycle. The various details of the mechanism within adhesive tape housing 72 and drive housing 84 are illustrated in FIGS. 8 to 10A.

10 The adhesive tape housing 72 is best shown in FIG. 10 as including a supply reel 86 and a take-up reel 88. The supply reel 86 is rotatably mounted upon shaft 90 and the take-up reel 88 is rotatably mounted on the driven shaft 92. The take-up reel 88 is driven and thus causes 15 the adhesive tape means 76 to be pulled along the various idler rollers 94 downwardly in the direction of arrows 96 and then within the feeder foot 70, and finally upwardly about the idler rollers 98 in the direction of arrow 100.

20 The tape means 76 is then wound upon the take-up reel 88.

25 As the adhesive tape means 76 is intermittently advanced to bottom idler roller 102, the tacky surface of a particular portion of the adhesive tape means 76 is presented to the topmost workpiece 26. As will be discussed in detail hereinafter, the movement of the adhesive tape means 76 is intermittent so that there will be a fresh or relatively fresh bit of tacky adhesive surface presented to the topmost workpiece 26 that will then be carried 30 above the serrated first transport rollers 78 by feeder foot 70 with the assistance of suction means 82.

35 As shown in FIG. 9 the shafts 90 and 92 extend from the adhesive tape housing 72 into the drive housing 84. In this way, the movement of the gearing within the 40 drive housing 84 is utilized intermittently to drive the shaft 92 which in turn causes intermittent revolving of the take-up reel 88. In view of the fact that the shafts 90 and 92 are secured to both adhesive tape housing 72 and drive housing 84, the housing 72 and 84 are movable together.

45 The mechanism which guides the feeder foot 70 through its cycle of lifting, kicking forward and return in the manner as illustrated in FIG. 10A, will be discussed in greater detail hereinafter. However, for present purposes, it should be noted that the movement shown in FIG. 10A is actually caused by the movement of support roller 74 and pivotal roller 104 (FIGS. 2 and 3). In particular, the support roller 74 can move vertically as well as pivot or rock; whereas the pivotal roller 104 can only pivot or rock.

50 Since feeder foot 70 is mounted (FIG. 10) on support roller 74, vertical movement of roller 74 is automatically converted to vertical movement of the feeder foot, and pivoting of the roller 74 causes pivoting of the feeder foot.

55 When the feeder foot 70 is in the intermediate full line position in FIG. 10A, the forward kicking of the feeder foot 70 to the roller feeding position 70" is accomplished because support roller 74 and pivotal roller 104 each pivot $7\frac{1}{2}$ ° in the clockwise sense as viewed in FIG. 10 so that the tape housing 72 (and drive housing 84) will be in the phantom position 70" of FIG. 10.

60 When the rollers 74 and 104 now pivot or rock backwardly in a counterclockwise direction for $7\frac{1}{2}$ °, the tape housing 72 returns to the intermediate full line position of FIG. 10, and the feeder foot 70 will be also in the intermediate neutral position with the workpiece 26 having been removed from the feeder foot 70 by passage between the rollers 78 and 80 to start the forward journey of the workpiece 26 toward the sewing station.

65 The feeder foot 70 will now descend to its lower pickup position 70' of FIG. 10A since support roller 74 moves vertically downwardly and also pivots for 15°. The pivotal roller 104 also tilts in a counterclockwise sense for 15 degrees. When the roller 74 completes its descent, the feeder foot will be in the lowermost position 70' of

FIG. 10A. When the roller 74 now lifts to the position of FIG. 10, the feeder foot 70 will be in the intermediate full line position of FIG. 10A.

It is to be noted that drive housing 84 (FIG. 9) is coupled to tape housing 72 so that downward travel of roller 74 also causes downward travel of drive housing 84 as well as tape housing 72 with feeder foot 70.

Particular reference is now made to FIG. 8 which shows a pin 106 secured about a short section of shaft 104 by clamp 107 and bolts 110. When the drive housing 84 drops downwardly with the downward travel of roller 74, the drive housing 84 will nest upon the pin 106 in such a manner that pin 106 will project within an opening 108 in the drive housing 84 (FIG. 8).

When the roller 74 moves upwardly and finally tilts backwardly (clockwise) so that the feeder foot 70 kicks to the roller feeding position 70", the entire adhesive tape housing 72 and drive housing 84 is also tilted backwardly or about roller 104 in a clockwise sense as generally indicated by the phantom position 72" of FIG. 10. When this occurs, the drive housing 84 again nests upon the pin 106.

Thus, the pin 106 will be located within the drive housing 84 two times as the feeder foot 70 passes through its various positions to make one cycle of movement. In other words when the feeder foot 70 drops down to the lowermost pick-up position 70' of FIG. 10A to pick-up a workpiece 26, pin 106 will project within drive housing 84, and when the feeder foot 70 lifts to the intermediate full line position of FIG. 10A and then kicks forwardly to the roller feeding position 70" of FIG. 10A, the pin 106 will again project within the drive housing 84.

Each time the pin 106 is nested with opening 108 of drive housing 84, the pin 106 is contacted by L-shaped rocker 112 which is pivoted about pivot point 114. Hence, when the pin 106 is contacted by the L-shaped rocker arm 112, the rocker arm 112 is caused to pivot in a clockwise sense about the pivot point 114 (as viewed in FIG. 8) against the bias of springs 116. This urges pawl 118 generally upwardly into engagement with a tooth of ratchet 120. An anti-reverse pawl 122, pivoted at 124 and suitably biased by spring 126, permits clockwise advancement of ratchet 120 in the direction of arrow 128 by virtue of the angle of inclination of the ratchet teeth, but the anti-reverse pawl 122 will wedgingly engage a ratchet tooth to prohibit counterclockwise rotation or retrogression of ratchet 120. The ratchet 120 is pivoted on stub shaft 130 as shown in FIG. 9 which also carries small concentric gear 132 that meshes with large gear 134. The large gear 134 is revolvably mounted upon the driven shaft 92 that is connected to take-up reel 88.

The net result of the foregoing is that when the feeder foot 70 kicks forwardly, the adhesive tape means 76 is advanced a bit, and as the feeder foot 70 is seated upon the topmost workpiece 26, the adhesive tape means 76 is again slightly advanced. By virtue of the foregoing, the adhesive tape means 76 is intermittently advanced from supply reel 86 to take-up reel 88.

The advancement of adhesive tape means 76 occurs after the feeder foot 70 has kicked forwardly and the workpiece 26 carried thereby forwardly is fed between roller 78 and 80 and is no longer in contact with the adhesive tape means 76. Another arrangement for the incremental timed advance of adhesive tape means 76 involves the use of an air valve acting against a spring loaded tape advancing member. In this arrangement, the air valve would be actuated a fraction of a second after the feeder foot 70 has kicked forwardly to insure that the workpiece 26 has been separated from the tape means 76. The activation of the air valve would cause the spring loaded member to move against its spring biasing, and in so doing actuate a ratchet wheel much in the manner that pawl 118 engaged a tooth of ratchet 120. Upon deactivation of the air valve the pawl would be withdrawn

to its former position and be ready to advance the ratchet again when the air valve is actuated.

Other details to be observed in FIGS. 8 to 10A include the fact that the drive housing 84 is secured upon support roller 74 by set screw assembly 136 (FIG. 8), and that couplings 138 are employed to secure portions of shafts 90 and 92 passing between the housings 72 and 84. Furthermore, as shown in FIG. 10 an indicator light 140 operated through leads 142 is provided to show when the take-up reel 88 is full. This is accomplished by arm 144 which will contact microswitch 146 of FIG. 10 when the take-up reel 88 reaches a predetermined size. When this occurs, a circuit is made, either to turn on or turn off the indicator light 140.

Incidentally, the couplings 138 may be utilized to facilitate the disconnection of the adhesive tape housing 72 from the drive housing 84. This is desirable when the take-up reel 88 is full, and it has been found to be the preferred practice to replace the adhesive tape housing 72 with a new housing 72, rather than trying to unwind the adhesive tape means 76 from the take-up reel 88, or even applying a new supply of adhesive tape to the shaft 90. It is rather preferred to replace the used untacky adhesive tape on take-up reel 88 at a point remote of the operation of the general machine 10 after housing 72 has been removed. Appropriate indicator means are also associated with adhesive tape means 76, in the event that the adhesive tape means 76 break or bind. Should the tape break, tension means (not shown) associated with the tape will be relaxed to close a microswitch in order to turn on a warning light or stop further movement of feeder foot 70.

The movement of the feeder foot 70 through the various positions of FIG. 10A is obtained by movement of pivotal roller 104 and support roller 74 which are secured together by means of coupling 148. The pivotal roller 104 is caused to rock, and the rocking action is conveyed to support roller 74 through the couplings 148. While the pivotal roller 104 is journaled in the machine frame and so can undergo rotational movement only, the support roller 74 can undergo linear movement as well as rotational movement as will be described hereinafter. Since the feeder foot 70 is secured upon the support roller 74, the feeder foot 70 will move up or down or kick forwardly in accordance with the rotational and linear movement of the support roller 74.

The movement of the rollers 74 and 104 is initiated through air actuated cranking means 150 which are shown in FIG. 2 as lying beneath table 152, and the cranking means 150 is shown in greater detail in FIGS. 12 and 13. The air valves associated with the cranking means 150 rock a short shaft 154 (FIG. 13) back and forth through a 180° sweep in order to rock eccentric 156 associated with shaft 154 through a 180° sweep between a first position as illustrated in FIG. 13 and a second position 180° removed therefrom. In the position of FIG. 13, rollers 159 extending from a disc 158 associated with the eccentric 156 makes contact with the terminals 162 of microswitches 160. When the eccentric is rocked for 180°, one of the rollers 159 extending from the nose 164 thereof is brought around in order to contact terminal 168 of microswitch 166. The cycle then repeats itself as the rollers 159 are returned in order to contact the terminals 162. As will be discussed in greater detail hereinafter, certain control circuitry may be associated with the microswitches 160 and the microswitch 166 that permits the eccentric 156 to rock back and forth between its two positions as previously described. This will have the effect of controlling the movement of the feeder foot 70 through its various positions. The control circuit will not only permit the time of the feeder foot movement to be varied, but also the control circuit will enable the feeder foot 70 to interrupt its cycle and start it again in the event the feeder foot 70 should fail for any reason to pick up a workpiece 26.

When the eccentric 156 rocks back and forth, it carries with it long rod 170 which has one end pinned at 172 to eccentric 156 and which has the other end thereof pinned at 174 to the upper end of link 176 that is pivotally connected to the frame at 178. Secured to the lower end of the link 176 is a short link 180 that is associated with gears 182, 184 and 186 which are a part of conventional paper feeding apparatus and serve to slowly raise the platform 28 as workpieces 26 are fed one by one therefrom by means of feeder foot 70 in order that the topmost workpiece 26 will be essentially at the same level at all times.

The air actuated cranking means 150 is of a construction known to the art and includes air heads 150A and 150B which are supplied by air through air inlet 150C. The air is directed against internal pistons (not shown) which are associated with a chain and sprocket arrangement (not shown) so that air is alternately admitted to one of the air heads 150A and then to the other air head 150B. This has the effect of oscillating short output shaft 154 through an alternating 180° sweep. As further shown in FIG. 12 the cranking means 150 are bolted to lower table 150D using brackets 150E and as shown in FIG. 2 the air head 150B is supplied through hose 158.

The gears 182, 184 and 186 are associated with the mechanism that will gradually raise the platform 28 as the workpieces 26 are fed one by one through the action of feeder foot 170. Each time the feeder foot 70 runs through its cycle through actuation of air actuated cranking means 150, link 176 is rocked as shown in FIG. 2 so that short link 180 will co-act with gear 182 in order to raise, from time to time, the platform 28 so that the topmost workpiece 26 will be maintained essentially at a constant level with respect to the under portion of feeder foot 70. The mechanism for gradually raising the platform 28 is well known in the paper sheet feeding or printing art and forms no part of the present invention.

FIG. 2 shows other details of the mechanism for gradually raising platform 28 including chain 188 with counterweight 190 that maintains the chain 188 in operative engagement with a sprocket (not shown) located behind gear 184 with counterweight 190 moving downwardly as the platform 128 gradually moves upwardly.

As further shown in FIG. 2 a rod 192 has one end secured to the link 176 at 194, with the other end of the rod 192 being secured at 196 to a sector-shaped cam 198 that is pivotally secured at 200 to the frame of the machine. It is thus seen that the rocking of eccentric 156 causes long rod 170 to reciprocate back and forth. This in turn causes rocking of the link 176 which leads to reciprocation of rod 192 that is secured at 194 to the link 176. The reciprocation of rod 192 in turn rocks cam 198 back and forth about pivotal securement 200.

As shown in FIG. 2, the cam 198 has a convex upper edge which consists essentially of a long relatively straight run 202 that merges into a short arcuate run 204. As the cam 198 pivots back and forth, the upper edge of the cam 198 contacts cam follower 206 which as shown in FIG. 2 has a contactor 208. Also secured to contactor 208 is the pivotal roller 104. The contactor 208 makes actual contact with the convex upper edge of cam 198. The cam follower 206 is spring biased into engagement with the upper edge of the cam 198 by spring means (not shown). Thus, as the cam 198 is rocked back and forth about pivotal securement 196, the contactor 208 of the cam follower 206 is caused to move in the opposite sense. Hence, when the cam 196 pivots in a counterclockwise sense about pivot point 200, the cam follower 206 will be moved in a clockwise sense, considering the outward extension of pivotal roller 104 as the pivot point since the pivotal roller 104 is secured to the cam follower 206.

It is thus seen that the rocking of cam 198 causes rocking of pivotal roller 104. As the cam 196 is rocked in a counterclockwise sense with contactor 208 riding upon long straight run 202 of the cam 198, the pivotal roller

104 will be rocked uniformly in a clockwise sense. When the contactor 208 reaches the short arcuate run 204, the pivotal roller 104 will be rocked more quickly since the arcuate run 204 is much steeper than the long run 202 of cam 198. This quicker movement of the pivotal roller 104 is actually converted through support roller 74 into the kicking action of the feeder foot 70 as it kicks forwardly to deliver a workpiece 26 to the serrated first transport roller 78.

As previously stated the pivotal roller 104 can only rock, and cannot move in a linear sense. However, the rocking of the pivotal roller 104 is converted through coupling 148 and guide cam 210 into rocking and linear movement of the transport roller 74 to which the feeder foot 70 is secured.

The support roller 74 can move linearly because it is not restrained in the manner that pivotal roller 104 is restrained. Since the feeder foot 70 moves with support roller 74, the rocking and linear movement of the support roller 74 cause the feeder foot 70 to move through its cycle of positions feeding the workpiece 26 to serrated transport roller 78.

The ends of support roller 74 have links 212 secured thereto from which extend a roller 214 (FIGS. 3 and 3A). As shown in FIG. 3A, the roller 214 moves against the guide cam 210 which is secured against the interior wall of panel 216.

The guide cam 210 has a long straight edge 218 which turns in an abrupt curve 220 into short horizontal run 222.

As will be described in the next paragraph, the guide cam 210 controls the linear movement of support roller 74 as the travel of roller 214 is controlled by straight edge 218 and short run 222 of guide cam 210. This occurs because the coupling 148 loosely embraces support roller 74 which is pinned at 224 to pivotal roller 104.

Thus, rocking of pivotal roller 104 in a clockwise sense as viewed in FIG. 3 causes end 226 of coupling 148 to rise since the other end of coupling 148 is pinned to roller 104. In this way the entire support roller 74 is lifted. In this stage of the cycle, the roller 214 is in the lower dashed position 214' of FIG. 3A, and thus the roller 214 will move upwardly against long straight edge 218 of guide cam 210 as pivotal roller 104 continues to rock in the clockwise sense.

Upward movement of the roller 214 will continue until abrupt curve 220 is reached when the roller 214 will be forced to travel in a generally horizontal path along short horizontal run 222. The abruptness of the change from straight edge 218 to horizontal run 222 is converted into an abrupt forward kicking action on the part of feeder foot 70. When the air actuated cranking means reverses direction, this reverses the direction of travel of cam 198. The pivotal roller 104 will be thereafter rocked in the opposite sense as the roller 214 will travel first for a short distance along horizontal run 222 and then downwardly along straight edge 218 in a reversal of the previous movement which has the effect of lowering the feeder foot 70 upon the next workpiece 26 to be fed.

The roller 214 may be suitably spring biased in order to provide a cushioning effect as it undergoes somewhat abrupt change of direction. It is to be further noted that when the roller 214 is moving upwardly or downwardly along straight edge 218 that it is essentially held rigidly in place except for the movement provided through the action of pivotal roller 104. In other words, the roller 214 will not freely move up or down unless the pivotal roller 104 rocks, and the roller 214, being biased into engagement with straight edge 218 will not move laterally.

However, when the roller 214 is moving horizontally along short run 222 it will float somewhat in the horizontal sense. This is because the support roller 74 is loosely held by end 226 of coupling 148 and when the roller 214 is travelling horizontally, there can be floating action or movement against the spring bias applied against the

roller 214. The purpose of the foregoing is to achieve a free but somewhat forwardly kicking action of feeder foot 70 in that part of the cycle. This is believed to add impetus to the forward thrust of the feeder foot 70, while creating a quick horizontal return action of the feeder foot 70 at such time as the workpiece 26 has been fed between serrated roller 78 and short complementary roller 80.

When the feeder foot 70 descends upon the topmost workpieces 26 so that the adhesive tape means 76 contact the topmost workpiece 26, the suction means 82 will become operative as soon as the feeder foot 70 has lifted a controlled short distance from its lowermost position. In this way, the picking up of more than one workpiece 26 at a time will be avoided as might occur if suction means 82 were operative at the instant the adhesive tape means 76 contacted the workpiece 26.

It is preferred that two or more spaced suction means 82 be provided in order to eliminate draping of the workpiece 26 as it is lifted. The spacing between the suction means 82 will be varied in accordance with the characteristics and dimensions of the particular workpiece.

The actual turning on of the vacuum in hose 288 leading to suction means 82 is controlled by a solenoid (not shown) which becomes operative after the elapse of a predetermined amount of time following the initiation of the rise of feeder foot 70.

In actual practice, the vacuum will be turned on about $\frac{1}{10}$ of a second after the feeder foot 70 has begun to lift. This time lapse should be sufficient so that the topmost workpiece 26 has been lifted an adequate distance away from the workpiece immediately below it so that the turning on of the vacuum will not cause the workpiece immediately below the topmost workpiece to be carried upwardly.

The suction means 82 provide for a steady grip upon topmost workpiece 26 as it is lifted and then fed forwardly between the rollers 78 and 80. As the feeder foot 70 kicks forwardly to deliver a workpiece to rollers 78 and 80, a cam (not shown) is mechanically tripped by the feeder foot in order to deactivate the solenoid that rendered the suction means 82 operative. It is desirable to turn off the vacuum in the suction means 82 just before the workpiece 26 is fed between the rollers 78 and 80 in order to minimize the resistance to forward feeding of the workpiece 26 as it is grabbed by the rollers 78 and 80. When the feeder foot 70 again has descended and starts to lift, the aforesaid timing device will become operative and reactivate the suction means 82 through a solenoid in the manner as previously described.

As previously stated, the platform 28 will be gradually urged upwardly as workpieces 26 are fed therefrom in order that the topmost workpiece 26 will be maintained essentially at a constant level. Should the feeder foot 70 accidentally feed more than one workpiece 26 at a time toward rollers 78 and 80, a reject mechanism is provided so that such a double layer will not be fed through the other elements of the automatic machinery. The reject mechanism basically comprises a thickness gauge 230 and a reject gate 232.

The thickness gauge 230 is mounted on a support member 234 which runs across the width of the apparatus. The thickness gauge 230 includes a feeling finger 236 which depends from bracket 238 that is secured to the member 234. The feeling finger 236 is vertically adjustable in order to accommodate materials having different thicknesses. In the event that two workpieces 26 are simultaneously fed between the rollers 78 and 80, the double thickness of such workpieces will make contact with the thickness gauge 230. The feeling finger 236 has a sensitivity such that a microswitch (not shown) will thereby be closed in order to actuate rejector solenoid 240 that will cause reject gate 232 to pivot counterclockwise as shown in FIG. 7 about point 242. When this happens, the double thickness of workpieces 26 cannot pass over reject gate

232 toward the sewing station 14. Instead, the open reject gate 232 acts as a trap door which deposits the double thickness of workpieces 26 downwardly into some convenient area for proper re-cycling. As shown in FIG. 7, the rejector solenoid 240 has a plunger 244 to which is pinned a rod 246 which in turn is secured at point 242 to the reject gate 232.

Also mounted on support member 234 is a light source photocell arrangement 248 which includes highly reflective surface 250 over which the workpieces 26 pass after leaving the rollers 78 and 80. The reflective surface 250 is positioned in such a manner that the light beam emanating from the light source will be reflected to the photocell at all times except when a workpiece 26 is moving upon reflective surface 250.

When the apparatus of the present invention is functioning normally, workpieces 26 will be fed one by one at predetermined intervals through rollers 78 and 80 and then across reflective surface 250 to roller 252 (FIG. 11).

As the leading edge of the workpiece 26 moves upon reflective surface 250, the path of light associated with photocell 248 is broken. This has the effect of holding feeder foot 70 in its forward kicking position until such time as the light beam can be reestablished, and more particularly when the workpiece 26 has passed completely beyond reflective surface 250. When this occurs, the light beam is reestablished, and the feeder foot 70 can now move backwardly and then downwardly upon the next workpiece 26. The aforesaid action is obtained through circuitry and an associated control means which will be described in greater detail hereinafter.

In the event the feeder foot 70 should fail to pick up a workpiece 26, the feeder foot 70 will continue to rise and then kick forwardly in its usual manner. Because the feeder foot 70 did not pick up a workpiece 26, it will not deliver any workpiece to the rollers 78 and 80, and therefore the light beam associated with photocell 248 will not be broken in the usual manner. When the light beam remains unbroken after forward kicking of the feeder foot, the circuitry associated with other control means to be described hereinafter, becomes operative in order after a predetermined short time interval to restart the feeder foot 70 through its cycle of movement. Hence, the feeder foot 70 is caused immediately to rock backwardly and then descend in an effort to pick up another workpiece 26. If the feeder foot 70 again fails to pick up a workpiece 26, it will still rise and then kick forwardly and then this cycle will repeat itself in the manner just described. Should this occur a predetermined number of times, such as four times, the aforesaid control means will turn off the feeder foot mechanism and activate an indicator light.

As shown in FIG. 7, a short roller 254 is positioned vertically above the roller 252 in order to transport the workpiece 26 toward and beyond reject gate 232 in the direction of transport belts 256.

As also shown in FIG. 7 the short rollers 80 are secured to a rod 258 which runs across the width of the apparatus whereas the short rollers 254 are pinned to a hold-down plate 260.

After the workpiece 26 passes over reject gate 232 it moves (FIG. 3) onto transport belts 256 with a portion of the workpiece 26 passing beneath preferably transparent plastic elongated fold plate 262 which extends from a point closely adjacent rollers 252 and 254 forwardly for a considerable distance toward the sewing station 14. The plate 262 is secured to and extends (FIG. 7) from a slightly elevated rod 264 which extends across the width of the apparatus. The fold plate 262 drapes gently toward and above reject gate 232 and then lays against two of the belts 256 (FIG. 3) for most of its length. The transport belts 256 are of the endless type and extend between driving rollers 266 and idler roller 268 (FIG. 3), although both of the rollers 266 and 268 may be driven, if so desired. The driving roller 266 is

driven by means of a pulley 270 which in turn is driven by motor arrangement 272 (FIG. 2).

As shown in FIG. 7 a support 274 is provided on one side of the machine adjacent driving roller 266 in order to hold one end of a cross rod 276 which extends across the width of the machine and has an end 278 secured in panel 216 (FIG. 3). The support 274 is also provided to hold one end of elongated air tube 280, the other end of which is secured upon support 282 (FIGS. 3 and 14). Air is fed to elongated tube 280 through air hose 284.

It is thus seen that as the workpiece 26 is fed over the reject gate 232 and then onto driving roller 266 as best seen in FIGS. 3 and 7, certain portions of the workpiece 26 will be interposed between the fold plate 262 and upon the transport belt 256. Other portions of the workpiece 26 not lying beneath the fold plate 262 will tend to lay against the transport belts 256.

However, the elongated air tube 280 has a plurality of spaced openings 286 formed therein, each of which face inwardly toward the transport belts 256. Hence, a series of jets of air 288 are delivered from the air tube 280. The air jets 288 tend to blow against elongated edge 290 of the workpiece 26 closest to air tube 280 as shown in FIG. 3 in such a way that the action of the air jets 288 causes edge 290 to double over upon fold plate 262. The continued presence of the air jets 288 maintains edge 290 in folded condition against fold plate 262 for a considerable portion of the travel of workpiece 26 via transport belts 256.

As shown in FIG. 7 the upper portions of the transport belts 256 after passing about driving roller 256, pass over short plate 292 which includes a lip 294 that acts to hold one edge of a stainless steel base 296. As the workpiece 26 travels along on transport belts 256 with edge 290 folded over as previously described, each workpiece 26 is fed beneath second hold down plate 298. A side guide 300 is provided which essentially runs along the length of the second hold down plate 298 but also extends slightly rearwardly of the plate 298. The side guide 300 terminates in an outwardly flared edge 302 which aids in guiding the folded edge 290 beneath the second hold down plate 298 which also possesses a flared entrance edge 304 to facilitate the entry of the workpiece 26 including folded edge 290 beneath second hold down plate 298.

In this connection a supplemental air tube 306 fed by compressed air hose 268 is provided that extends into the flared entrance edge of hold down plate 298 so that the air jet emanating from the supplemental air tube 306 is directed against folded edge 290 of the workpiece 26 in the manner as shown in FIG. 14. The side guide 300 is supported by means of an upstanding plate that is adjustable held in position through adjustment means 310 as shown in FIG. 14.

The workpiece 26 with folded edge 290 is now conveyed under support rod 312 and then upon idler roller 268 into sewing area 14 and particularly upon sewing area bed 314 that is adjustably mounted on posts 315 which extend from the sewing station carriage. As shown in FIG. 3, the workpiece 26 will be transported to a point beneath the sewing head 316 since the trailing edge of the workpiece 26 will still be located upon transport belts 256 that will continue to urge the entire workpiece 26 toward the sewing head 316.

Other details to be observed on FIG. 2 are the compressed air and vacuum supply means 318 which are of a construction well known to the art. As further shown in FIG. 2, the entire feeder station 12 as well as the section of the apparatus between the rollers 266 and 268 are mounted upon a single carriage 320 that rolls on ground engaging wheels 322. This facilitates the transportation of the entire feeder station, as well as allowing the feeder station 12 to be temporarily rolled away whenever varying combinations of sewing machines, such as the pleating machine and a buttonhole making or button sewing machines are aligned in series. This will be

discussed in greater details hereinafter, but as shown in FIG. 2, the sewing station 14 is mounted upon a carriage 324 that is supported on ground engaging wheels 326 that run in a direction perpendicular to the wheels 322 (see also FIG. 1A).

As further shown in FIG. 2, a spring loaded lever 328 is provided upon the carriage 320 to control a resilient knob 330 which as shown in greater detail in FIG. 1B abuts against the side of the carriage 324 in order to prevent movement of the carriage 324 with respect to the carriage 320. Similar levers with resilient knobs are positioned upon other sewing sections to be discussed hereinafter that will be aligned in series after the carriage 324.

As shown in FIG. 15 a spring biased idler roller 332 is positioned immediately above idler roller 268. The ends of the roller 332 (FIG. 16) are journaled in side plates 333 that are pivoted at 334 to bar 335 and also adjustably supported on a rod 336, with the plates 333 bearing upon coil spring 337 that is adjustably positioned about the rod 336 using knob 338.

When the workpiece 26 with folded edge 290 passes upon driven roller 268, it actually moves between the nip of the opposed rollers 268 and 332 and is advanced toward the sewing station 314 and particularly sewing head 316, and in so doing passes beneath sewing guide 340 (FIG. 15) that is preferably of a transparent material. The workpiece 26 is then moved along sewing area bed 314 toward a wheel 342 supported on shaft 343 of hold down device 344. The hold down device 344 is so constructed that the wheel 342 will be held above the sewing area bed 314 whenever a workpiece 26 is being fed toward the sewing head 316 until such time as the workpiece 26 has passed beneath the sewing head 316 and the sewing head has begun to operate upon the workpiece 26.

After the elapse of a predetermined time following the start of the sewing head 316 as initiated by the interruption of a light beam emanating from second light source photocell arrangement 346, the hold down device 344 will be pivoted downwardly so that the wheel 342 contacts the workpiece 26 which is now being advanced under the sewing head 316.

The hold down device 344 comprises two elongated parallel arms 348 (FIG. 16) which are supported upon the rod 312 by means of clips 350 that nest beneath portions of rod 312, with the clips 350 being secured to the arms 348 by means of adjustable bolts 352. The elongated parallel arms 348 are secured together by short links 354. As shown in FIG. 16, the shaft 343 of wheel 342 of the hold down device 344 is revolvably secured to the parallel arms 348 at 356 and 358.

The wheel 342 of hold down device 344 is held above sewing area bed 314 in order to allow a workpiece 26 to pass beneath the sewing head 316. The hold down device 344 is then pivoted downwardly by the rocking of support rod 312 so that the wheel 342 will contact the workpiece 26.

The aforesaid pivoting of the hold down device 344 is accomplished by operation of air cylinder 360 as best shown in FIGS. 15 and 16. The reciprocating action of the air cylinder 360 has the effect of rocking support rod 312 either upwardly or downwardly. Since, the hold down device 344 is secured to the rod 312 by means of clips 350, this will have the effect of lowering or raising the wheel 344.

The operation of the air cylinder 360 (FIG. 15) has the effect of alternately raising and lowering a pin 362 which extends upwardly from the air cylinder 360. The air cylinder 360 is actuated through compressed air fed into it by way of hose 364.

As shown in FIG. 15A, the upper end of the pin 362 is secured to a leg 366 of U-shaped bar 368. The other leg 370 of the bar 368 has an opening (not shown) which permits the passage of a threaded stem 372 of a long

bolt having a head 374. As further shown in FIGS. 15A and 16, an actuating finger 378 is operatively secured to the threaded stem 372. This is accomplished by providing an opening in the actuating finger 378 so that the actuating finger 378 may be slipped upon the threaded stem 372 in a manner as indicated in FIG. 15A so as to be interposed between the coil springs 376. A nut 380 (FIG. 15A) holds the entire assembly together.

It is thus seen that upward movement of pin 362 as caused by the operation of air cylinder 360 will have the effect of urging the bar 368 upwardly, and therefore carrying one end of actuating finger 378 upwardly. However, the other end 382 of actuating finger 378 is rigidly secured to support rod 312 by means of nut 384 (FIG. 16). The support rod 312 is, however, revolably secured at each end in the plates 333. Thus, upward movement of one end of actuating finger 378 will have the effect of causing the support rod 312 to rock in a given direction since the other end 382 of actuating finger 378 is secured to an extension of one end of support rod 312, and also since the support rod 312 is revolvably received in the plate 333.

In view of the foregoing, the raising of the pin 362 will cause the support rod 312 to rock counterclockwise as viewed in FIG. 15 or FIG. 16. Since the hold down device 342 is secured to the support rod 312, counterclockwise rocking of the support rod 312 will cause the entire hold down device 344 to pivot in a counterclockwise sense as viewed in FIG. 15, and so the wheel 342 will be moved downwardly upon a workpiece 26 that is already beneath the sewing head 316.

The workpiece 26 must already be under the sewing head 316, because the wheel 342 will be moved upon a workpiece 26 only after the elapse of a predetermined short time following the breaking of the light beam associated with the light source-photocell arrangement 346. As previously discussed, the light beam will be broken only when the leading edge of a workpiece 26 passes under the light source-photocell arrangement 346 that is positioned at the sewing head 316.

As further shown in FIGS. 15 and 16, a spring finger 386 is secured upon the shaft 343 of the wheel 342. Thus, when the wheel 342 is moved downwardly to contact a workpiece 26, the spring finger 386 is also moved downwardly to contact the workpiece 26 in order to facilitate passage beneath sewing head 316.

Other details to be observed in the sewing area (FIG. 15) and particularly in connection with the sewing head 316 include sewing needle 388 and presser foot 390. As shown in FIG. 16 a mirror 392 is provided in the sewing area in order to reflect the light beam emanating from photocell arrangement 346, and to direct such a light beam to the photosensitive head of the arrangement 346. As further shown in FIG. 15, the sewing head also includes a bracket 394 to which is secured by way of knob 396 a supplemental bracket 398 which supports an arcuate binding guide 400. As further shown in FIG. 15, binding 402 is threaded through the guide 400 and then under the presser foot 390. As the presser foot 390 operates in a conventional manner in cooperation with a feed dog, the binding 402 will be drawn downwardly through and beyond the presser foot 390 by the action thereof at the same time as the workpiece 26 is drawn beneath the sewing head 316 in connection with the operation of the sewing needle 388.

Where desired, an auxiliary feed device (not shown) may be associated with the sewing head 316. Such an auxiliary device can include a driven belt which contacts the workpiece and may be made operative whenever the hold down device 344 is actuated to move wheel 342 downwardly into contact with a workpiece 26. The auxiliary feed device belt is operable through a separate drive taken from the sewing machine motor and the belt is driven at such time as it is moved into contact with a workpiece 26 that has passed under the sewing head 316.

It should be noted, that when the light beam of the photocell arrangement 346 is broken, that this has the immediate effect of turning on the sewing machine. Furthermore, when the trailing edge of a workpiece 26 has passed beyond the sewing machine, thereby re-establishing the light beam, the sewing machine will be turned off, and the hold down device 344 will be raised through downward movement of pin 362 as initiated by the operation of air cylinder 360. This also causes the raising of spring finger 386, and auxiliary feed device that may be associated with the hold down device 344.

In a preferred operation of the present invention, the auxiliary feed device may be operated by a connection to the sewing machine motor so that as soon as the sewing machine is turned on, the moving belt of the auxiliary feed device will also become operative. As will be discussed in greater detail hereinafter, the turning on of the sewing machine will also be accompanied with the start of a separate control mechanism which is operated on the basis of a count of the number of stitches made by the sewing machine.

While the belt of the auxiliary feed device will be moving, the auxiliary feed device itself will still remain elevated above the workpiece 26 until the necessary predetermined amount of time has elapsed that permits the air cylinder 360 to become operative to move the hold down device 344 downwardly into contact with a workpiece 26. The auxiliary feed device is preferably coupled to the hold down device 344 so that the hold down device 344 and the auxiliary feed device are actuated at the same time to move toward the workpiece 26.

After the workpiece 26 moves beyond the sewing area 14, it passes between driving feed roller 404 (FIG. 18) and opposed roller 406. As shown in FIG. 1, endless transport belts 408 extend about the driving feed roller 404 and also about idler roller 410 much in the manner of the transport belts 256. Where desired, tensioners for the transport belts (not shown) may be provided in order to obtain the desired belt tension and spacing.

Therefore, as the workpiece 26 emerges from the sewing area 14, it is pulled by the action of the rollers 404 and 406 onto the transport belts 408 and then carried toward cutter 412. As shown in FIG. 18 the opposed roller 406 is revolvably secured upon a plate 414 which is pivotally secured at 416 to support 418. The other end of plate 414 is resiliently biased through coil spring 420 to frame 422 by having one end of coil spring 420 anchored to the frame 422.

The driving feed roller 404 is revolvably secured to the frame 422 and is driven by moving belt 424 (FIG. 19). The belt 424 is engaged by driving gear 426, and the belt 424 also passes about second gear 428, and, of course, the driving feed roller 404 as shown in FIG. 19.

The driving gear 426 receives its power from motor 430 which drives shaft 432 to which the gear 426 is attached. As also shown in FIG. 19, a second shaft 434 extends from second gear 428, with third gear 436 being secured to the other end of the shaft 434. A second belt is engaged by the third gear 436, and the second belt 438 also passes about fourth gear 440. It is thus seen that the belt 424 not only drives feed roller 404, but also has the effect of driving second belt 438.

As further shown in FIG. 19, shaft 442 couples fourth gear 440 to gear 444. A belt 446 is driven by the gear 444, and the belt 446 also passes about supplemental gear 448. It is thus seen, that movement of second belt 438 causes movement of the belt 446.

Further attention is called to FIG. 19 which shows that the supplemental gear 448 secured to one end of long shaft 450 which passes through support 452, with wheel 454 being secured to the other end of long shaft 450. A rod 456 is eccentrically secured at 458 to the wheel 454, and the other end of the rod 456 is secured to a finger 460 which is spring biased via coil spring 462. The finger 460 is supported by the rod 464 and actuating link

466 is secured to the finger 460 for movement therewith. As the movement of the belt 446 causes long shaft 450 to rotate, and also wheel 454 to revolve, the eccentric coupling of rod 456 to the wheel 454 causes the rod 456 to undergo a crank action as the wheel 454 rotates. As shown in FIG. 19, the rod 456 is spring biased by virtue of coil spring 468.

Thus, the cranking of rod 456 causes finger 460 to oscillate back and forth about its connection to rod 464. This has the effect of urging actuating link 466 back and forth. As generally shown in FIG. 18, the oscillating link 466 is associated with gear 470 which in turn meshes with the gears 472, 474 and 476 through certain intermediate gears.

The gears 470, 472, 474 and 476 are a part of a conventional paper feeding raising and lowering mechanism, much in the manner of link 180 and gears 182, 184 and 186. As the workpieces 26 become stacked in alternating bundles 478 and 480, the stacking platform 482 is gradually lowered so that the height of the topmost workpiece 26 that has just been fed through the stacking area will remain essentially constant. A chain 484 and a counter-weight 486 are associated with the gradual lowering mechanism in a well known manner.

As soon as a workpiece 26 no longer passes beneath the light source-photocell arrangement 346 associated with sewing head 316, the light beam thereof is re-established. This has the effect of causing cutter 412 to reciprocate back and forth across the width of the apparatus above transport belts 408 in a manner as best shown in FIGS. 25, 26, 27 and 28.

As previously stated, the transport belts 408 carry the workpieces one by one from the sewing area 14 through and beyond cutter 412. In a preferred form of construction, the re-establishment of the light beam in the photocell arrangement 346 after the trailing edge of a workpiece 26 has passed beyond sewing head 316, sends a signal to the cutter 412 which causes it to move across the width of the apparatus and thereby perform a cutting operation on a workpiece 26 which lies in the path of the cutting blade.

The cutter 412 basically comprises a motor 488 (FIG. 25) which continuously rotates circular cutting blade 490. The cutting blade 490 is reciprocated back and forth across the width of the apparatus by the action of a chain drive 492 (FIG. 25) that drives a belt 494 to which is secured a carriage 496 that supports the cutting blade 490. The carriage 496 is moved back and forth along track 498 in a manner as shown in FIGS. 27 and 28.

As shown in FIG. 25, the blade 490 is fitted with a guard 500 with the guard 500 also serving to hold shaft 502 (FIG. 27) that supports blade 490. As shown in FIG. 27 the carriage 496 possesses a V-notch 504 in order to accommodate the blade 490.

The details of the carriage 496 as located in the track 498 are shown in FIG. 26 wherein the carriage 496 is shown as being secured to the upper surface of belt 494 by means of bolts 506. It is thus seen that movement of belt 494 in a given direction causes the carriage 496 along with cutting blade 490 to be slid with respect to stationary track 498 across the width of the apparatus. As shown in FIG. 28, the base of the carriage 496 is rather narrow and terminates adjacent between the first and second transport belts 408. It is contemplated that an auxiliary base (not shown) will be added to the base of the carriage 496, with the auxiliary base extending for approximately one half the distance across the apparatus. The auxiliary base can be used to avoid any hindering action that may be exerted upon a workpiece 26 when it passes across the convex edges (FIG. 27) of track 498 in the direction of the arrow shown in FIG. 27.

The carriage 496 is reciprocated back and forth by a mechanism which is shown in greater detail in FIGS. 25 and 27. Such mechanism is actuated by air cylinder 508 with supply hoses 510. The operation of the air cylinder

508 causes reciprocation in and out of shaft 512. A toothed rack 514 is secured to the shaft 512 by means of post 516 and a first gear 518 is in operative engagement with the rack 514. The first gear 518 is secured to a second gear 520 by means of shaft 522. The second gear 520 meshes with a third gear 524 (FIG. 25) that is secured to driving shaft 526. A sprocket 528 for driving the chain 492 is secured to the shaft 526. An idler sprocket 530 is secured on stub shaft 532 in order to support chain 492.

It is thus seen that operation of air cylinder 508 causes reciprocation of shaft 512. This in turn causes first gear 518 to rock back and forth in response to the motion of rack 514. The rocking of first gear 518 is conveyed through second gear 520 to third gear 524 which in turn causes 15 rocking or oscillation of driving shaft 526 which drives chain 492 through sprocket 528. The chain 492 has a connecting clip 534 secured thereto which includes a nose 536 that is held captive in a slot in belt 494. Thus, reciprocation of chain 492 is directly conveyed to belt 494 through connecting clip 534. Since the carriage 496 is secured to the belt 494 as shown in FIG. 26, the reciprocating action of air cylinder 508 actually causes carriage 496 with associated cutting blade 490 to reciprocate back and forth across the width of the apparatus in response 20 to a predetermined signal.

When air cylinder 508 operates to reciprocate shaft 512, motor 430 which drives transport belts 408 may either be turned off or disengaged by a clutch mechanism (not shown) from causing the transport belts to move. 25 Thus, when carriage 496 reciprocates back and forth to cut a workpiece 26, the workpiece 26 will be stationary. As soon as the carriage 496 completes its stroke the motor 430 again drives the transport belts. The aforesaid action is achieved by tying in the operation of motor 430 and air 30 cylinder 508 through appropriate relays so that when air cylinder 508 operates, motor 430 will not be effective to drive belts 408.

The workpiece 26 is now in condition to be stacked in one of the bundles 478 and 480. Attention is called to 40 FIG. 21 wherein a workpiece 26 is conveyed via transport belts to roller 410.

In travelling through the stacking section, the workpiece 26 is carried by transport belts 408 to upper roller 538 and lower roller 540 which cause the workpiece 26 to pass 45 downwardly to long reciprocable tray 542 as best seen in FIG. 21. The conveying of the entire workpiece 26 to the tray 542 is materially assisted by the action of moving belt 544 that causes the workpiece 26 to be brought closely adjacent to the rearmost end of the apparatus, and in such a way that the entire workpiece 26 is positioned upon the tray 542.

As the workpiece 26 nears the rearmost end of the apparatus, it passes beneath stacker photocell 546. This has the effect of interrupting the light beam emanating 55 from the stacker photocell 546 and thereby causing the tray 542 to retract or reciprocate forwardly in tracks 548 (FIG. 24) so that the workpiece 26 is dropped or deposited upon other workpieces 26 that are deposited in bundles 478 and 480 upon stacking platform 482.

60 When the light beam associated with the stacker photocell 546 is broken, a signal is sent by means of appropriate circuitry to air cylinder 550 (FIG. 21). The air cylinder 550 is mounted through legs 552 upon frame 554, and is supplied through air hoses 556. The operation of the air cylinder 550 has the effect of causing spring loaded plunger 558 with associated short rack 560 to reciprocate back and forth. The short rack 560 meshes with a gear 562 which is attached to a shaft 564 that passes through shafts 556, and has large ratchet 65 wheel 568 secured to the opposite end thereof as shown in FIGS. 20 and 21. A chain 570 passes about ratchet wheel 568, and also extends about upper small ratchet wheel 572 which is associated with and which causes a drum 574 to turn. A gear 576 also turns with the drum 574, and the gear 576 meshes with small gear 578.

As further shown in FIG. 20 a connecting rod 579 extends from the first gear 578 to a second small gear 578, with both of the gears 578 being secured on supports 580.

Both of the small gears 578 mesh with long rack 581 which is secured to the undersurface of the reciprocable tray 542 along each side thereof.

It is thus seen that when the light beam associated with stacker photocell 546 is broken the air cylinder 550 becomes operative to cause short rack 560 to move outwardly. This has the effect of urging gear 562 and therefore endless chain 570 in a counterclockwise sense as viewed in FIG. 21. Since the drum 574 turns with the endless chain 570, and since the gear 576 turns with the drum 574, the gear 576 will be rotated in a counterclockwise sense. This has the effect of causing small gears 578 to rotate in a clockwise sense as viewed in FIG. 21. Since the long racks 581 mesh with one of the gears 578, this has the effect of causing the long racks 581 and therefore the tray 542 to retract forwardly, and thus the workpiece 26 which was on the tray 542, and which cannot move forwardly with the retracting action of the tray 542 and the opposing motion of belt 544 will then drop by gravity upon other workpieces 26 which were previously deposited on the stacking platform 482.

After the air cylinder 550 has moved the plunger 558 forwardly to its maximum position, the air cylinder 550 then acts to move the plunger 558 rearwardly. The rearward or return stroke of the plunger 558 has the effect of now urging endless chain 578 in a clockwise sense, and in this way the long racks 581 are urged rearwardly, and the tray 542 is therefore urged rearwardly to the full line position of FIG. 21 to await the deposit of another workpiece 26 and the interruption of the light beam associated with the stacker photocell 546 so that the aforesaid operation can repeat itself.

When the tray 542 returns to its rearwardly extended position a tamper 582 is thrust upon the bundles 478 and 480 in order to force them downwardly upon stacking platform 482 to produce more compact bundles. In this way, the capacity of the stacking mechanism will be effectively increased, although this is an optional feature of the present invention.

The tamper 582 is shown in greater detail in FIG. 23 as being supported by rods 584 which are secured to the underside of the tray 542. As shown in FIG. 20, the rods 584 are secured to the underside of the tray 542 through pins 585 extending therefrom. The details of the tamper 582 are shown in FIG. 23 wherein the tamper 582 consists of two end rollers 586 which are adjustably mounted in slots 587 of parallel plates 588 which support the end rollers 586. The end rollers 586 each have pins 590 which extend through the rods 584 and are mounted in the slots 587 of the plates 588.

As further shown in FIG. 23, there is also a middle roller 592 which has pins 594 which permit the roller 592 to be mounted in the plates 588. Coil springs 596 extend between middle roller 592 and one of the end rollers 586 in order to provide greater resiliency of the rollers 586 and 592 as enhanced by the floating action of the rollers 586 within limits permitted by the extent of the slot 587.

As shown in FIG. 21, the tamper 582 is somewhat suspended from the tray 542 by the relatively long rods 584. When tray 542 retracts, it moves forwardly a considerable distance as indicated in the phantom lines of FIG. 21. As an optional feature of the invention, a wiping bar 598 (FIGS. 21 and 24) is provided to extend across a portion of the width of the apparatus immediately below tracks 548 as shown in FIG. 24. When tray 542 retracts and carries tamper 582 with it, the rods 584 come in contact with the wiping bar 598, and the rods 584 are wiped upwardly so as to be positioned between

tray 542 and the wiping bar 598 as shown in FIG. 24 as the tray 542 nears its forwardmost position.

When the tray 542 again moves rearwardly toward the full line position of FIG. 21, the rods 584 move clear of the wiping bar 598, and the tamper 582 is dropped with force upon the bundles 478 and 480 of workpieces that are stacked on the stacking platform 482. In this way, a tamping force is exerted upon the bundles 478 and 480.

As previously described, the workpieces 26 pass one by one beneath stacker photocell 546 under the urging of moving belt 544. A mirror 600 is provided (FIG. 20) in order that the light beam emanating from the light source of the stacker photocell arrangement 546 will be reflected to the detector element of the stacker photocell arrangement 546. When this light beam is broken by the passage of a workpiece 26, the tray 542 retracts as previously described.

As shown in FIGS. 20, 21 and 22, the stacker photocell arrangement 546 is mounted upon a cross member 602. The cross member 602 is rendered movable by being mounted at one end thereof upon a wheel 604 that may travel upon a bar 606. The other end of the cross member 602 is simply slidably mounted in a track 607.

By virtue of the foregoing arrangement, the stacker photocell will be located at all times in one of two positions as illustrated in FIG. 21. The extended position is shown in phantom in FIG. 21 and the retracted position is shown in full line in FIG. 21.

As will be described hereinafter, the stacker photocell 546 will be moved from time to time from its extended position to its retracted position, and in so doing, the alternating bundles 478 and 480 on the stacker platform 482 will be formed. When the stacker photocell 546 is in its full line retracted position of FIG. 21, the light beam associated with the stacker photocell arrangement will be broken at a point somewhat remote from the tray 542, and thus a bundle 478 will be produced so long as the stacker photocell 546 is in its retracted position. When the stacker photocell arrangement is extended to the phantom position of FIG. 21 a bundle 480 is created. It is thus seen, that the alternating bundles 478 and 480 are compiled in accordance with the retraction and extension of the stacker photocell arrangement 546.

The number of workpieces 26 in a particular bundle 478 or 480 can be controlled by using a counter which will send a signal to the means for retracting or extending the photocell arrangement 546 after a predetermined number of workpieces 26 have been deposited upon the stacking platform 482. This will cause a change of position in the stacker photocell arrangement 546, and the counter will be reset so that after a predetermined number of workpieces 26 have been deposited into a new bundle in accordance with the position of the stacker photocell arrangement 546, the position of the stacker photocell arrangement will again be changed in order to achieve the alternating bundles as shown in FIG. 21.

The position of the stacker photocell arrangement 546 is changed by the action of air cylinder 608 as best shown in FIG. 22. The air cylinder 608 has air hoses 609 associated with it with cylindrical housing 610 extending therefrom. The intermittent reciprocating action of the air cylinder 608 alternately causes a reciprocal rod 612 either to be extended as shown in FIG. 22 or to be retracted, and the stacker photocell 546 is accordingly extended or retracted with the intermittent reciprocation of the reciprocal rods 612. When the rod 612 moves outwardly, one end of the cross member 602 slides in the track 607 while the other end of the cross member 602 rides on bar 606 with the help of wheel 604. It is thus seen, that alternating bundles 478 and 480 may be deposited, and this will be of great help in forwarding the work through other stations for additional processing.

As previously discussed, the belt 544 moves the workpieces 26 one by one rearwardly upon the tray 542 until

the light beam emanating from the stacker photocell arrangement 545 is broken. As shown in FIG. 21, the belt 544 is an endless belt which passes about roller 538 and then to rollers 614 and 616 which are revolvably mounted upon parallel plates 618 as shown in FIGS. 20 and 21.

The belt 544 then passes about rear small roller 620 and doubles back about front small roller 622, finally returning to the roller 538.

It is preferred that the belt 544 be separately driven, although the movement of transport belts 408 can be relied upon to drive the belt 544 through an appropriate gear arrangement as shown in FIGS. 20 and 21. The movement of transport belts 408 about roller 410 causes the roller 410 to revolve about its axis. A first gear 624 (FIG. 21) is associated with the roller 410, and the gear 624 meshes with idler gear 626 as best shown in FIG. 21. The idler gear 626 meshes with a second gear 628 that is associated with roller 540. By virtue of the foregoing arrangement, the movement of transport belts 408 is used to rotate roller 540. The rotation of roller 540 is in turn conveyed to roller 538 by appropriate gearing. In this way, the roller 538 is caused to rotate, and since the belt 544 passes about the roller 538, the entire belt 544 will be moved through rotation of roller 538.

As shown in FIG. 20 the ends 630 of roller 540 are journaled in frames 632, and the ends of rollers 616, 618, 620 and 622 are journaled in supports 633. The frames 632 are bolted to suitable angle pieces 634 and 635 which extend from the basic framework of the apparatus as shown in FIG. 20.

The stacking platform (FIG. 20) rests upon a stacker carriage 636 which is secured to chain 484 through link 637. Thus, as the chain 484 slowly descends with the accumulation of workpieces 26 on stacking platform 482 as permitted through the action of actuating link 466, the stacker carriage 636 will descend as guided by channel 638.

As shown in FIG. 18, the entire stacking area is supported upon stacker base 639 from which depends ground engaging wheels 640 that are mounted at 642 on the base 639. As also shown in FIG. 18 a section of the apparatus which includes the cutter 412 is mounted upon wheels 634. It is thus seen by virtue of the foregoing arrangement and with reference to FIG. 1A that the present apparatus is actually composed of a series of sections including feeder carriage 320, sewing station carriage 324 and cutter section 646.

As shown in FIG. 18C the apparatus of the present invention can actually be built from a series of sections. For instance, two different kinds of sewing machines can be interposed between the feeding section on one hand and the cutting and stacking sections. The first sewing machine can be a pleating machine with the second sewing machine being a buttonhole maker or a button sewer with the two sewing machines cooperating in order to perform operations upon a shirt or blouse front. Clearly, there are many combinations of finishing machinery on the market which can be assembled in an arrangement similar to FIG. 18C in order to perform a plurality of operations upon a workpiece 26. Appropriate timing apparatus may be utilized in order to coordinate the various operations of feeding, the plurality of sewing actions, and the cutting and stacking operations.

As previously discussed spring loaded levers 328 (FIG. 1B) are utilized in connection with the bringing together of certain of the sections which are to be built up to form the apparatus of the present invention. As shown in FIG. 1A, the sewing station carriage 324 includes sewing area bed 314 as supported upon posts 315. Also as shown in FIG. 1A there are supports such as bar 335 and support members 648 and 650 which are a part of the support arrangement for feeding area bed 652 and cutting area bed 654.

When the stacking platform 482 has received a desired number of workpieces 26, it is preferred to wheel away

the stacking station and to replace it with a new stacking station rather than physically removing the bundles from the stacking station. In order to be certain that the apparatus will not operate when the loaded stacking station 18 is being wheeled away and before a new stacking station 18 is installed in its place, an arrangement such as that shown in FIG. 18A is utilized. As shown in FIG. 18A undersurface 656 of cutter section 646 is fitted with magnets 658 which will contact iron bars 660 which extend from stacker base 639. The undersurface 656 also has a microswitch 662 extending therefrom with the microswitch 662 having a contactor element 664 which will be closed by abutment against bar 666 of stacker base 639 whenever the stacker base 639 is positioned adjacent undersurface 656 in the manner as shown in FIG. 18A. When a loaded stacker station 18 is wheeled away, the contactor element 664 will move outwardly of the microswitch 662 under spring pressure, thereby opening a circuit that will halt further operation of the apparatus until another stacker station 18 is moved adjacent the cutter section 646 so that the microswitch 662 is again closed.

As previously noted, the stacker platform 482 will gradually descend as workpieces 26 are deposited thereon. The stacker platform 482 as shown in FIG. 18B is essentially a board having a plurality of openings 668 which permit the passage of vertical guide rods 670 that guide the stacking platform 482 in its vertical movement. As shown in FIG. 18 the guide rods 670 have free upper ends 672 and are secured at their lower ends to stacker base 639.

Where desired, a scaffold arrangement 674 such as shown in FIG. 29 may be utilized in order to support additional rollers or miscellaneous devices that will act upon a workpiece 26 as it is passing through the apparatus of the present invention. For instance, the scaffold arrangement 674 may be placed on the apparatus between the sewing station and the cutting station.

The scaffold arrangement 674 includes supports 676 from which risers 678 extend. The risers 678 support cross rods 680 which in turn support cross bars 682 through clips 684. As shown in FIGS. 30 and 31 the clips 684 include forked arms 686 that terminate in arcuate fingers 688 which nest about a portion of the cylindrical surface of the cross rods 680. The forked arms 686 terminate upwardly in base 690 (FIG. 30) which receives a set screw 692 with a threaded stem 694 that passes through base 690 in bearing contact with a cross bar 682 which is received between forked arms 686.

As shown in FIG. 29, certain of the clips 684 also support L-shaped brackets 696, with the foot 698 thereof being positioned upon the base 690. The brackets 696 also include upwardly extending arms 700 through which pass upper cross rods 702. The upper cross rods 702 support upper cross bars 704 through the use of upper clips 706 in a relationship substantially identical to cross rods 680, cross bars 682 and clips 684.

The cross rods 682 may be used to support various auxiliary devices such as roller 708 which includes parallel arms 710 that are supported on a cross rod 680. A wheel 712 is revolvably mounted on the arms 710 and the collars 714 are provided in order to maintain the roller 708 on the cross rod 680. A short rod 716 extends between the arms 710 at a point remote from the wheel 712, with the rod 716 being used to secure one end of coil spring 718, the other end of which is secured to upper cross bar 704.

It will be readily appreciated by those skilled in the art that the scaffold arrangement of FIG. 29 offers various levels and points of support for auxiliary devices.

In operation workpieces 26 are placed in a stacked arrangement upon platform 28 as shown in FIG. 5 and retention fingers 52 adjusted to maintain the configuration of the pile of workpieces 26. As the workpieces 26 are fed

one by one by means of feeder foot 70, the platform 28 will gradually rise in order to maintain the topmost workpiece 26 at an essentially constant level.

The feeder foot 70 is located closely adjacent to a workpiece 26 at the start of the feeder foot cycle. The feeder foot 70 moves downwardly to contact the upper surface of a workpiece 26 through the adhesive means 76 associated with the feeder foot 70. The feeder foot 70 then starts to lift and suction means 82 become operative in order to assist in the lifting action. The feeder foot 70 lifts to a maximum height and then kicks forwardly to deliver the workpiece 26 to rollers 78 and 80. As the feeder foot 70 moves through its cycle, a fresh bit of tacky adhesive surface is provided by the nesting of pin 196 within opening 108 of drive housing 84 as best illustrated in FIG. 8. This has the effect of urging pawl 118 into engagement with ratchet tooth 120 in order to intermittently advance adhesive tape means 76 between supply reel 86 and take-up reel 88.

The feeder foot 70 is caused to travel through its cycle of movement as shown in FIG. 10A by the operation of pivotal roller 74 and support roller 104. The pivotal roller 104 can undergo rotational movement only while support roller 74 can undergo linear movement as well as rotational movement.

The movement of rollers 74 and 104 is initiated through air actuated cranking means 150 as shown in FIG. 2. The cranking means 150 causes long rod 170 to reciprocate back and forth. This has the effect through rod 192 of rocking cam 198 back and forth about pivotal securing 200. The cam 198 has a convex upper edge which is contacted by cam follower 206 that has a contactor 208 to which is secured pivotal roller 104. The contactor 208 makes actual contact with the convex upper edge of rocking cam 198, and cam follower 206 is spring biased into engagement with the upper edge of cam 198. Thus, as cam 198 is rocked back and forth the contactor 208 is caused to move in the opposite sense. Since pivotal roller 104 is secured to contactor 208, the rocking of cam 198 by cranking means 150 has the effect of rocking pivotal roller 104. The rocking of pivotal roller 104 is converted through coupling 148 and guide cam 210 into rocking and linear movement of the transport roller 74 to which the feeder foot 70 is secured.

The support roller 74 can move linearly because it is not restrained in the manner that pivotal roller 104 is restrained. Since the feeder foot 70 moves with the support roller 74, the rocking and linear movement of the support roller 74 cause the feeder foot 70 to move through its cycle of positions feeding the workpiece 26 to through its cycle of positions feeding the workpiece 26 to serrated transport roller 78.

The actual movement of the support roller 74 is controlled by roller 214 in connection with guide cam 210.

By virtue of the movement of the roller 214 the entire support roller 74 is raised and lowered as well as thrust back and forth. Furthermore, when the roller 214 is moving horizontally along short run 222 of cam 210, it will float somewhat in the horizontal sense.

When the feeder foot 70 descends upon the topmost workpieces 26 so that the adhesive tape means 76 contact the topmost workpiece 26, the suction means 82 will become operative as soon as the feeder foot 70 has lifted for a predetermined short time from its lowermost position. In this way, the picking up of more than one workpiece 26 at a time will generally be avoided as might occur if suction means 82 were operative at the instant the adhesive tape means 76 contacted the workpiece 26.

The vacuum and suction means 82 is turned off just before the workpiece 26 is fed between rollers 78 and 80 in order to minimize the resistance to forward feeding of the workpiece 26 as it is grabbed by the rollers 78 and 80. The vacuum is turned off when a cam is mechanically tripped by the forward kicking action of the feeder foot.

In the event the feeder foot 70 accidentally picks up

more than one workpiece 26 at a time, a reject mechanism including thickness gauge 230 and reject gate 232 will open to prevent the travel of such a double layer through the apparatus of the present invention.

If the feeder foot 70 has fed a workpiece 26 to the rollers 78 and 80, the workpiece 26 will be fed beneath pick-up photocell arrangement 248 that actuates a timer cycle which will prevent the operation of the feeder foot 70 for short controllable intervals. This will achieve proper spacing of the workpieces 26 as they move down the apparatus of the present invention.

If the feeder foot 70 fails to pick up a workpiece 26, a control mechanism will become active so that the feeder foot 70 will immediately repeat its cycle. If the feeder foot 70 fails to pick up a workpiece 26 for a predetermined number of times another control means will turn off the mechanism.

The workpiece 26 is now moved toward the sewing station 14 by transport belts 256. The workpiece 26 passes upon fold plate 262 and air jets 288 emanating from tube 280 tend to blow the elongated edge 290 of the workpiece in such a way as to cause edge 290 to double over upon fold plate 262. The folded workpieces are then fed beneath a hold down plate 298 and a supplemental air tube 306 associated therewith provides an additional air jet in order to facilitate the passage of the folded workpieces.

The folded workpiece 26 then enters sewing station 314 and passes beneath sewing guide 340 (FIG. 15). As this occurs, the workpieces 26 also pass beneath hold down device 344.

After the elapse of a predetermined short time following the start of the sewing head 316 as initiated by the interruption of a light beam emanating from sewing machine light source photocell arrangement 346, the hold down device 344 will be pivoted downwardly so that the wheel 342 of device 344 contacts the workpiece 26 which is now being advanced under the sewing head 316.

The aforesaid pivoting of the hold down device 344 is accomplished by operation of air cylinder 360 as best shown in FIGS. 15 and 16. The operation of air cylinder 360 has the effect of alternately raising and lowering a pin 362 which urges actuating finger 378 upwardly, and this has the effect of causing support rod 312 to rock in a given direction. In this manner the hold down device 344 which is secured to support rod 312 will be pivoted so that wheel 342 contacts workpiece 344.

The operation of air cylinder 360 will take place only after the workpiece 26 has moved under sewing head 316. This is achieved by the operation of a time delay mechanism that is actuated with the breaking of the light beam associated with the sewing machine photocell arrangement 346. The air cylinder 360 becomes effective after a pre-determined short time delay in order to permit the workpiece 26 to have passed under the wheel 342 before the hold down device 344 including the wheel 342 is moved downwardly by the operation of air cylinder 360.

When the hold down device 344 moves downwardly to contact the workpiece 26, it carries with it spring finger 386 in order to simulate the fingers of a human operator in feeding the workpiece 26 through the sewing area. Where desired, an auxiliary feed device (not shown) may be associated with the sewing head 316. Such an auxiliary device will include a driven belt that becomes operative as soon as the light beam associated with the sewing machine photocell arrangement 346 is broken. However, the auxiliary feed device is not actually lowered upon the workpiece 26 until the hold down device 344 is actuated.

As soon as the sewing machine photocell arrangement 346 is actuated, the sewing machine clutch engages and the sewing action starts.

In many adaptations of the present invention the workpiece 26 passes from the sewing area and is then acted upon by a secondary sewing machine, such as a button-hole sewer or a button sewer. The sewing action of the primary and secondary sewing machines or of other de-

vices which may be inserted following the primary sewing machine is controlled by reference back to the number of stitches sewn by the primary sewing machine. A counting and control mechanism is actuated and then deactivated by reference to a predetermined number of stitches that have been sewn, as will be described hereinafter.

After the workpiece 26 moves beyond the sewing area, it passes between driving feed roller 404 (FIG. 18) and opposed roller 406 so that the workpiece 26 is carried onto transport belts 408 toward cutter 412.

The driving feed roller 404 receives its power through gear 426 that is driven by motor 430. The motor 430 also drives a second belt 438 which as shown in FIG. 19 is eventually connected to an actuating link 466. This has the effect through gears 470, 472, 474 and 476 of gradually lowering stacking platform 482 as workpieces 26 become stacked thereon in alternating bundles 478 and 480.

When a workpiece 26 no longer passes beneath the sewing machine photocell arrangement 546, the light beam thereof is re-established. This has the effect of causing cutter 412 to reciprocate back and forth one time across the width of the apparatus above transport belts 408 in a manner as shown in FIGS. 25 to 28. When the cutter 412 reciprocates across the apparatus, the transport belts 408 will stop so that the workpiece 26 will be stationary when the cutter 412 becomes operative.

The motor 488 of the cutter 412 continuously rotates circular cutting blade 490. The cutter 412 is caused to reciprocate back and forth by operation of chain drive 492 (FIG. 25) that drives a belt 494 to which is secured reciprocal carriage 496 that supports the cutting blade 490. The carriage 496 is moved back and forth through the action of air cylinder 508 as shown in FIGS. 25 and 27. The operation of air cylinder 508 causes gear 518 to rock back and forth one time in response to the motion of rack 514. The rocking of the gear 518 is then conveyed through other gearing to driving shaft 526 which drives chain 492 through sprocket 528. The chain 492 has a connecting clip 534 secured thereto which is held captive in a slot in belt 494, and in this way the reciprocation of chain 492 is directly conveyed to belt 494.

The workpiece 26 is now in condition to be stacked in one of the bundles 478 and 480. In travelling through the stacking station the workpiece 26 is carried by transport belts 408 to upper roller 538 and lower roller 540 which cause the workpiece 26 to pass downwardly to long reciprocable tray 542 through the action of moving belt 544.

As the workpiece 26 nears the rearmost end of the apparatus it passes beneath stacker photocell arrangement 546. This has the effect of interrupting the light beam emanating from the stacker photocell arrangement 546 and thereby causing the tray 542 to retract or reciprocate forwardly in tracks 548 so that the workpiece 26 is dropped or deposited upon other workpieces 26 that are already deposited on stacker platform 482 in bundles 478 and 480.

When the light beam associated with the stacker photocell 546 is broken, a signal is sent to air cylinder 550 (FIG. 21). The operation of the air cylinder 550 has the effect of reciprocating for one time spring loaded plunger 558 and rack 560 associated therewith. The aforesaid reciprocating action is carried through a chain 570 and finally to small gears 578 which mesh with long racks 588 secured to the undersurface of the reciprocable tray 542 along each side thereof in order to reciprocate tray 542.

After the air cylinder 550 has moved the plunger 558 forwardly to its maximum position, the air cylinder 550 then acts to move the plunger rearwardly. The rearward or return stroke of the plunger 558 has the effect of now urging endless chain 578 in the opposite sense in order that the tray 542 will be brought rearwardly to its fully extended position to await the deposit of another workpiece 26.

When the tray 542 returns to its rearwardly extended

position, a tamper 582 is thrust upon the bundles 478 and 480 in order to force them downwardly upon stacking platform 482 to produce more compact bundles.

The tamper 582 (FIG. 21) is somewhat suspended from the tray 542 by the relatively long rods 584. When the tray 542 retracts, it moves forwardly a considerable distance and carries tamper 582 with it. As the tray 542 retracts, the rods 584 come in contact with wiping bar 598 which extends across the width of the apparatus immediately below tracks 548. This has the effect of wiping the rods 584 upwardly so as to be positioned between tray 542 and wiping bar 598 as shown in FIG. 24.

When the tray 542 again moves rearwardly toward the full line position of FIG. 21, the rods 584 move clear of wiping bar 598 and the tamper is dropped with force upon the bundles 478 and 480 of workpieces that are stacked on the stacking platform 482 in order to exert a tamping force thereon.

The stacker photocell arrangement 546 will be located at all times in either an extended position as shown in phantom in FIG. 21 or in the full line retracted position of FIG. 21.

The stacker photocell arrangement will be moved from time to time from its extended position to its retracted position, and in so doing the alternating bundles 478 and 480 on the stacker platform 482 will be formed.

When the stacker photocell 546 is in its full line retracted position of FIG. 21, the light beam associated therewith will be broken at a point somewhat remote from the far end of the tray 542, and thus a bundle 478 will be produced so long as the stacker photocell arrangement 546 is in its retracted position. When the stacker photocell arrangement is extended to the phantom position of FIG. 21, somewhat near the end of the tray 542, a bundle 480 is created.

It is thus seen, that the alternating bundles 478 and 480 are compiled in accordance with the retraction and extension of the stacker photocell arrangement 546. The number of workpieces 26 in a particular bundle 478 or 480 and the number of bundles 478 and 480 can be controlled by using various control counters. In particular, one form of counter sends a signal to the means for retracting or extending the photocell arrangement 546 after a pre-determined number of workpieces 26 have been deposited upon the stacking platform 482 in order to change the position of the stacker photocell arrangement 546. At this time the counter will be reset so that after a pre-determined number of workpieces 26 have been deposited into a new bundle in accordance with the new position of the stacker photocell 546, its position will again be changed in order to achieve the alternating bundles as shown in FIG. 21.

The position of the stacker photocell 546 is changed by the action of air cylinder 608 as best shown in FIG. 22. The intermittent reciprocating action of the air cylinder 608 alternately causes a reciprocal rod 612 to be either extended or retracted, and the stacker photocell 546 is accordingly extended or retracted. When the rod 612 is moved outwardly by the action of air cylinder 608, one end of the cross member 602 which supports the stacker photocell 546, slides in the track 607, while the other end of the cross member 602 rides on the bar 606 with the help of the wheel 604.

It is thus seen that the present invention completely automates the sewing process. Attention is now referred to FIGS. 32, 33 and 34 which show the wiring diagrams of control circuits which coordinate the various components of the present invention.

The circuitry for controlling the action of feeder foot 70 is shown in FIG. 32. Power is provided to the circuits of FIG. 32 through the power sources shown therein. The circuit leading to normally closed contact r_3 is powered by a 110-volt alternating current source when the switch associated with the circuitry in the right hand section of FIG. 32 is closed.

As shown in FIG. 32 the two upper microswitches are open, and therefore power can essentially flow only through normally closed contact r_3 to the normally closed contact of r_{1-1} and then to S_2 which is a solenoid that drives air actuated cranking means 150 in a clockwise sense. This has the effect of driving the two cams 159' which are mechanically coupled together in a clockwise sense. Although a circuit is also made to R_4 which is the feeder foot photocell arrangement relay, the current ordinarily flowing in such a circuit is extremely small until the light beam associated with feeder foot photocell arrangement 258 is broken, when a large current flows in the circuit and closes the normally opened contact r_4 in the circuit.

When power flows through S_2 , the two cams 159' are rotated in a clockwise sense, and this has the effect of causing the feeder foot 70 to descend slightly to the lowermost point of its cycle so that adhesive tape means 76 contacts the topmost workpiece 26 which is about to be fed from platform 28. As the cams 159' continue to revolve in a clockwise sense, the feeder foot means 70 lifts to its maximum position and then kicks forwardly to deliver the workpiece 26 to the rollers 78 and 80. At this point, the cams 159' have moved a full one half rotation from the position shown in FIG. 32 so that their pointers are now directly down instead of up as shown in FIG. 32.

When the right hand cam 159' of FIG. 32 begins to pivot in a clockwise sense, a roller which it was contacting is now free to pivot in a counterclockwise sense under spring loading, and therefore the upper right hand microswitch of FIG. 32 will now close. When the cam 159' rotates for a full 180° so that its pointer is down, the lower roller is contacted, and this has the effect of closing the lower microswitch.

At this point, a circuit is made to R_1 which is the relay which controls the operation of air actuated cranking means 150. This causes normally open contact r_{1-2} to close, and this contact will latch in the closed position. The turning on of relay R_1 has the effect of closing the normally open contact, and opening the normally closed contact of the contact pair r_{1-1} . When this occurs, power now flows to solenoid S_1 instead of solenoid S_2 , and this has the effect of reversing the operation of air actuated cranking means 150.

The two cams 159' now begin to pivot in a counterclockwise sense until the upwardly pointing position of FIG. 32 is reached. As soon as the cams 159' begin to pivot in a counterclockwise sense, the lower microswitch will open, but power will continue to be fed to relay R_1 because of the latching action of contact r_{1-2} . However, when the cams 159' have reached their upwardly pointing position of FIG. 32, the upper microswitch opens. This has the effect of opening the circuit to relay R_1 and the condition of the contact pair r_{1-1} again changes to that shown in FIG. 32.

Therefore, the net effect is again to feed power to solenoid S_2 but not to feed power to solenoid S_1 . When the cam pair 159' pivoted in the counterclockwise sense, the feeder foot 70 retracted and then moved downwardly to a position just above the next workpiece 26 that is positioned on platform 28.

If there were no other circuitry associated with the feeder foot 70, it would continuously feed workpieces 26 toward the sewing station. However, the feeder foot 70 can move so rapidly that it is desired to introduce a time delay after it has gone through its cycle. This is the reason for the presence of feeder foot photocell arrangement 248.

It will be recalled that the workpiece 26 passes over the reject gate 232 and then beneath the photocell arrangement 248. At this point, the light beam associated with the photocell arrangement 248 is interrupted, and a relatively large current flows in the circuit of photocell amplifier relay R_4 . This has the effect of closing normally open contact r_4 and timer T will operate.

Incidentally, it should be noted that air actuated cranking means 150 which actually drives feeder foot 70 will operate so long as relay R_3 is turned off since normally closed contact r_3 passes power to either of the solenoids S_1 or S_2 . Power is also fed to vacuum time delay relay R_2 which closes normally open contact r_2 that introduces the vacuum action after the feeder foot 70 has operated for a short time period in order to be sure that the feeder foot 70 has now started its lifting action so that the vacuum will not cause more than one workpiece 26 to be drawn against adhesive tape means 76.

Attention is now referred to the left circuit of FIG. 32 which illustrates what happens when the timer T is rendered operative by the breaking of the light beam associated with the photocell arrangement 248, and also what happens when work is not fed and therefore the light beam of photocell arrangement 248 is not broken.

In the latter case, the circuitry of FIG. 32 causes the feeder foot 70 to function almost immediately and cancels out any time delay action. This is most desirable in the event of failure to pick up, since there is no reason to have a time delay.

Both cams 159' are coupled to pivot together so that when the cams 159' return to their upwardly pointing position of FIG. 32, the left hand cam contacts a roller which closes a left microswitch of FIG. 32. The pulser of the left circuitry has been previously built up, and with the closing of the left microswitch, the pulser dumps its charge through the master control relay R_3 . It should be remembered that the air actuated cranking means 150 will operate so long as the relay R_3 is turned off. Conversely, when the relay R_3 is turned on, the air actuated cranking means 150 no longer operate until the master relay R_3 is again turned off.

When the pulser dumps its charge upon the closing of the left microswitch, the relay R_3 comes on momentarily and closes the normally open contact r_{3-1} . This makes a circuit which includes normally closed contact t_1 , now closed contact r_{3-1} and normally closed contact r_{5-2} . The aforesaid circuit also leads to master relay R_3 , and thus the master relay R_3 is held on, at least so long as the normally closed contact r_{5-2} remains in the normally closed position.

As soon as master relay R_3 is energized, the feeder foot 70 no longer operates for reasons previously discussed. When the master relay R_3 is energized, the normally opened contact r_{5-2} is closed and a circuit is also made through rapid cycle time delay relay R_5 . At the expiration of a pre-determined time, less than three seconds, contact r_{5-2} is opened and contact R_{5-1} is closed.

At this point, further action depends upon whether a workpiece 26 has interrupted the light beam associated with photocell arrangement 248. If the light beam has been interrupted, the normally open contact r_4 is closed and timer T becomes operative. This has the effect of closing normally opened contact t_2 . Since the master relay R_3 is now on, this closes contact r_{3-1} , and power may still be fed to the master relay R_3 through normally closed contact t_1 , now closed contact r_{3-1} and closed contact t_2 .

This circuit will continue to be closed even after the time delay relay R_5 has come on and opened the normally closed contact r_{5-2} . Thus, the master relay R_3 will be held on until the timer T has operated through its period of time delay.

At the conclusion of the time delay period, the normally closed contact t_1 opens, and this has the effect of opening the circuit to the master relay R_3 . The master relay R_3 is therefore deenergized, and the contact r_3 now closes in order to start the action of the air actuated cranking means 150 by feeding power to either of the solenoids S_1 or S_2 in a manner as previously described.

In the event that the feeder foot 70 has failed to pick up a workpiece 26, the light beam associated with the photocell arrangement 248 is not broken, and the action

which leads to the immediate operation of the feeder foot 70 will be described.

When the cams 159' have returned to their upwardly pointing position of FIG. 32 the left microswitch is closed which causes the pulser to dump its load through the master relay R₃. As previously stated, a circuit is made through the relay R₃ which includes normally closed contact t₁, now closed contact r₃₋₁ and normally closed contact r₅₋₂. When the master relay R₃ is energized, the action of the air actuated cranking means 150 ceases.

Also, when the master relay R₃ is energized, the normally open contact r₃₋₂ is closed and power is fed to time delay relay R₅. When the contacts of relay R₅ are switched after a pre-determined short time interval, the normally closed contact r₅₋₂ will be opened.

Since the timer T has not operated because the workpiece 26 has not been fed, the combination of the normally open contact t₂ and the now open contact r₅₋₂ turns off to master relay R₃. This has the effect of closing contact r₃ and the feeder foot 70 will operate almost immediately.

It is thus seen that either the timer T will operate in order to defeat the effect of time delay relay R₅ and hold master relay R₃ on, or the time delay relay R₅ will have the effect of turning off master relay R₃ in order to initiate the cycle of feeder foot 70.

The circuitry associated with the sewing area as shown in FIG. 33 wherein the closing of a switch feeds power to relay R₁ which is actually the sewing machine photocell arrangement 346. Thus, when a workpiece 26 interrupts the light beam associated with the photocell arrangement 346, the sewing machine relay R₁ is energized, and this has the effect of closing normally open contact r₁₋₁. This feeds power to sewing machine clutch solenoid S₁ and starts the operation of the first sewing machine. Power is also fed to a delay circuit which after a pre-determined time interval causes the hold down device 344 to become operative through solenoid S₂. Power is also fed to the rear conveyor motor so that the workpiece 26 now beneath the photocell arrangement 346 will be carried toward the cutter 412. Finally, power is also fed to a billing counter C₁ in order to produce a record of the operation of the present invention for financial purposes.

As further shown in FIG. 33, the interruption of the light beam associated with the photocell arrangement 346 closes normally open contact r₁₋₃, and power is fed to a stitch counter. It is preferred that the stitch counter be operative after a pre-determined number of stitches (referred to as a low count), and that the stitch counter becomes inoperative after another pre-determined number of stitches (referred to as the high count) have been sewn. For instance, the stitch counter can be set at values of 30 and 40. This means that after 30 stitches have been sewn, a secondary action will be initiated, and that 10 stitches later, the secondary action will be halted. Such secondary action can be incorporated within the primary sewing machine, such as, shirring or pleating, or can be the operation of a secondary sewing machine for purposes of sewing a buttonhole or a button, with the secondary sewing machine being located downstream of the primary sewing machine.

Also as shown in FIG. 33 is a reset device C₂ which causes the stitch counter to repeat its action either not at all (setting No. 1) or to repeat the action once (setting No. 2) or to repeat the action twice (setting No. 3). In other words, if the reset device C₂ is on setting 3, and if the stitch counter is set at 30 and 40, the secondary sewing machine will become operative at the 30th stitch, will turn itself off at the 40th stitch, will become operative at the 70th stitch, will turn itself off at the 80th stitch, will become operative at stitch 110, and will finally turn itself off at stitch 120. Obviously, the reset device C₂ can be constructed to provide more than two repetitions.

Reference is now made to the small circuit diagram in the lower left corner of FIG. 33 which is powered by a

12-volt alternating current source. When the light beam associated with the sewing machine photocell 346 is interrupted, relay R₁ is energized as previously discussed. This has the effect of opening normally closed contact r₁₋₂. When the light beam associated with the photocell arrangement 346 is no longer interrupted, the relay R₁ is deenergized and the contact r₁₋₂ becomes closed. The net effect is that the pulser then dumps its charge through cutter solenoid S₄ so that the cutter 412 advances across a workpiece 26.

Meanwhile relay R₂ is energized with the operation of reset device C₂ so that the contact r₂ is closed and power is fed to the secondary device solenoid S₂, such as a button-hole sewing machine, a button sewing machine, a shirring or pleating machine. This current also powers the knife of the cutter 412. However, the cutter 412 will advance only at such time as the relay R₁ is deenergized at which time contact r₁₋₂ becomes closed.

The circuitry associated with the stacking mechanism of the present invention is shown in FIG. 34 wherein the stacker photocell arrangement 546 is represented by the relay R₁. When the light beam associated with the stacker photocell arrangement 546 is interrupted, the relay R₁ is energized and the contact r₁₋₁ is closed in order to actuate the solenoid S₁ which initiates the operation of air cylinder 550 which drives tray 542.

When stacker relay R₁ is energized, contact r₁₋₂ is also closed in order to retract or extend the photocell arrangement 546 from time to time in order to produce the alternating bundles 478 and 480.

With reference to the right side of the circuitry of FIG. 34, there is provided a pile counter and a bundle counter. Each time the tray 542 reciprocates, a signal is sent to the pile counter. When a pre-determined number of signals 35 have been sent to the pile counter which corresponds to the number of workpieces 26 desired in a particular pile, the pile counter sends signals to the bundle counter and also the bundle shift control C.

The bundle counter is set to permit a pre-determined 40 number of bundles to be established on stacking platform 482, and then the apparatus will be automatically turned off.

Each time a signal is sent to bundle shift control C, the bundle shift solenoid S₂ is actuated in order to operate air cylinder 608 so that the stacker photocell arrangement 546 is either extended or retracted in order that the alternating bundles 478 and 480 will be produced. Finally, FIG. 34 shows a reset switch in the circuit of the bundle counter, the reset switch being the microswitch 662 which will prevent all operation of the present apparatus when a stacker section loaded with alternating bundles 478 and 480 is wheeled away and prior to the substitution of a new stacking section.

It is to be noted that many types of goods, such as 55 sleeve or shoulder goods may be sewn with the apparatus of the present invention. Also, various safety devices well known to those skilled in the art may be installed in the circuitry of the present invention. If desired, manual control of the operation of the various elements of the present invention may be introduced for troubleshooting purposes.

Obviously, many modifications and variations of the present invention are possible in the light of the above teachings. It is, therefore, to be understood that within 60 the scope of the appended claims, the invention may be practiced otherwise than as specifically described.

What is claimed as the invention is:

1. An automatic sewing apparatus having automatic feeding means for workpieces of porous cloth stacked into at least one pile, said apparatus including a sewing machine, said feeding means including reciprocable feeder foot means operative to contact the topmost workpiece in said pile and to separate said workpiece from the remainder of the pile, said feeder foot means having adhesive means for engagement with said topmost workpiece to

achieve an initial lifting action, said feeder foot means further including vacuum means activated immediately after said initial lifting action, said vacuum means upon activation assisting said adhesive means in maintaining contact with said feeder foot and said workpiece during continued lifting action thereby feeding said workpiece toward said machine for sewing.

2. The invention of claim 1 wherein said adhesive means are tacky and said feeder foot means includes lowering means to lower said feeder foot means to contact said topmost workpiece, said feeder foot means also including raising and forwardly thrusting means to feed said workpiece to transport rollers with said vacuum means becoming operative upon said workpiece a predetermined short time interval following the start of said initial lifting action.

3. The invention of claim 2 including pin means extending from said feeder foot means to engage said topmost workpiece and assist in delivering said workpiece to said rollers.

4. The invention of claim 3 wherein said pin means extends from said vacuum means.

5. An automatic sewing apparatus for performing at least one operation upon workpieces of porous cloth assembled into a pile, said apparatus comprising automatic feeding means for said workpieces, said feeding means including reciprocable feeder foot means being operative to contact the topmost workpiece in said pile and to separate said workpiece from the remainder of the pile, said feeder foot means having adhesive means in contact with said topmost workpiece to achieve an initial lifting action, said feeder foot means further including vacuum means which becomes operative during said lifting action, said vacuum means assisting said adhesive means in maintaining contact with said workpiece during continuing lifting action, said sewing apparatus further including a sewing station, cutting means and stacking means, said sewing station including a sewing machine and means to actuate the sewing machine in response to the feeding of said workpieces by said feeding means, means adapted to actuate said cutting means in response to the movement of said workpieces through said sewing station and means adapted to actuate said stacking means in response to the movement of said workpieces beyond said cutting means.

6. The invention of claim 5 wherein said adhesive means are tacky and feeder foot means includes lowering means to lower said feeder foot means to contact said topmost workpiece, said feeder foot means also including raising and forwardly thrusting means to feed said workpiece to transport rollers, with said vacuum means becoming operative upon said workpiece a predetermined short time interval following the start of said lifting action.

7. The invention of claim 6 including pin means extending from said feeder foot means to engage said topmost workpiece and assist in delivering said workpiece to said rollers.

8. The invention of claim 7 wherein said pin means extends from said vacuum means.

9. The invention of claim 6 including a platform holding said pile of workpieces are provided in a pile on a platform, means to gradually raise said platform as said workpieces are fed by said feeder means in order to maintain the topmost workpiece at an essentially constant level, and retention fingers extending over said platform to maintain said pile and to minimize the feeding of more than one piece of cloth at a time.

10. The invention of claim 6 including a pivotal roller and a support roller to actuate said feeder foot means, said feeder foot means being mounted on said support roller, air actuated cranking means for rocking said pivotal roller, said support roller being coupled to said pivotal roller for rotational and linear movement.

11. The invention of claim 10 including a first cam being rocked by said air actuated cranking means, the rocking of said first cam causing rocking of said pivotal

roller, and a second cam guiding the rotational and linear movement of said support roller.

12. The invention of claim 6 wherein said vacuum means is deenergized by mechanical tripping means triggered during the forward thrusting action of said feeder foot means.

13. The invention of claim 6 including reject means downstream of said feeder foot means to prevent the downstream travel of multiple pieces of cloth.

14. The invention of claim 6 wherein said feeding means include time delay means to prevent said feeder foot means from operating for a short, controllable interval in the event the feeder foot means has fed a piece of cloth.

15. The invention of claim 14 wherein said feeding means includes means to cause said feeder foot means immediately to repeat its cycle in the event the feeder foot means has failed to feed said workpiece, feeder photocell means downstream of said feeder foot means to detect said workpieces and means to deenergize the feeder foot means in the event of a predetermined number of failures.

16. The invention of claim 6 including a sewing machine photocell means adapted to initiate action of the sewing machine upon passage of said workpiece, a hold-down device also moving against said piece of cloth after elapse of a predetermined time period and means to actuate said hold-down device.

17. The invention of claim 6 including a secondary sewing device located downstream with respect to a first sewing machine.

18. The invention of claim 6 including means to energize a conveyor belt upon actuation of said feeder photocell means and stop means to deenergize said conveyor belt after passage of a piece of cloth, said cutting means including a cutter with said stop means energizing said cutter to reciprocate back and forth one time to cut said workpiece, said cutter having a blade which is continuously operated.

19. The invention of claim 18 wherein moving belt means cause said workpiece to travel from said cutter to a long reciprocable tray by moving belt means, stacker photocell means to cause said tray to reciprocate one time in order to deposit said workpiece on a stacker platform, means to gradually lower said platform as said pieces of cloth are deposited in order to maintain the topmost piece of cloth at an essentially constant level.

20. The invention of claim 19 including means to move said stacker photocell means in a predetermined controllable cycle back and forth between and extended in a retracted position in order to form alternating bundles of pieces of cloth.

21. The invention of claim 19 wherein said stacking means includes a tamper adapted to be thrust upon workpieces deposited upon said stacker platform.

22. The invention of claim 6 including a stitch counter in said sewing area and actuated by the machine flywheel, said stitch counter initiating a count after a second predetermined number of stitches and reset means to repeat said action a predetermined number of times in accordance with said first and second predetermined number of stitches.

23. The invention of claim 6 including a fold plate downstream of said feeder foot means and air jet means directed toward said fold plate to fold a portion of a previously fed piece of cloth over said fold plate and transport belts downstream of said fold plate to carry said piece of cloth toward said sewing station.

24. An automatic sewing apparatus having automatic feeding means for workpieces of porous cloth stacked into at least one pile, said apparatus including a sewing machine, said feeding means including reciprocable feeder foot means operative to lift and deliver to said sewing machine the topmost workpiece in said pile and to separate said workpiece from the remainder of the pile, said

feeder foot means including vacuum means and further including pin means, said vacuum means exerting a sufficient lifting action only upon said topmost workpiece to separate said workpiece without carrying along any other workpieces, said pin means engaging said topmost workpiece and assisting in delivering said workpiece forwardly relative to the remainder of the pile with the continued movement of said feeding means toward said sewing machine.

25. The invention of claim 24 wherein said pin means extend from said vacuum means.

26. The invention of claim 25 wherein said workpieces are a permanent press fabric with said vacuum means exerting a static vacuum of five to nine inches of mercury so that only one workpiece at a time will be picked up by said feeder foot means.

27. The invention of claim 26 wherein said feeder foot means also has adhesive means for engagement with said topmost workpiece.

28. In a combined sewing apparatus including a sewing machine, a cutter, and a stacker having a stacker platform, moving belt means carrying a workpiece from said cutter to a long reciprocable tray, stacker photocell means causing said tray to reciprocate one time for depositing said workpiece on said stacker platform, means

15

10

20

25

to gradually lower said platform as said workpieces are deposited thereon thereby maintaining the topmost workpieces at an essentially constant level, means to move said stacker photocell means in a predetermined controllable cycle back and forth between an extended position for locating a first stack and a retracted position for locating a second stack offset from said first stack and thereby presenting alternating bundles of workpieces.

29. The invention of claim 28 wherein said stacking means includes a tamper adapted to be thrust upon workpieces deposited upon said stacker platform.
